SUPERVISORY CONTROL SYSTEM

James T. Purcell, Secane, Pa., assignor to General Electric Company, a corporation of New York

Application February 27, 1946, Serial No. 650,619

20 Claims. (Cl. 177—353)

1

My invention relates to supervisory control systems for supervising and controlling apparatus units in a remote station from a control station such as a dispatcher's office.

One object of my invention is to provide an improved arrangement for selecting a desired apparatus unit and controlling the operation of the selected apparatus unit.

Another object of my invention is to provide a new type of code selector supervisory control system which can share the interconnecting channel with other signalling facilities.

A further object of my invention is to provide a supervisory control equipment which may be operated over a two-wire metallic circuit through insulating transformers or over the simplified type of carrier channel with only very minor changes being required to change from one type of channel to the other.

A still further object of my invention is to provide a new and improved all relay supervisory control system which may be readily changed to take care of additional apparatus units as the system requirements change.

In accordance with a preferred embodiment of my invention, I employ an all relay equipment in which all of the codes contain the same number of current impulses but differ from each other only by the length of the time interval between one or more of the current impulses.

My invention will be better understood from the following description when taken in connection with the accompanying drawings, and its scope will be pointed out in the appended claims.

In the embodiment of my invention shown in the drawings, which comprise Figs. 1 to 6, inclusive, the supervisory control system is designed to provide control and indication for five remote apparatus units shown in Fig. 6 as circuit breakers AU1 to AU5, inclusive. The apparatus and circuits shown in Figs. 1 to 3, inclusive, are those located at the control station or dispatcher's office while the apparatus and circuit shown in Figs. 4 to 6, inclusive, are those located at the remote station which is connected to the dispatcher's office by two line conductors L1 and L2.

At the dispatcher's office, there is provided a separate group of control keys and indicating lamps for each apparatus unit to be selected and controlled in the remote station. Each group of keys includes a two-position select key, such as SK1 for apparatus unit AU1, SK2 for apparatus unit AU2, etc., which is operated by the dispatcher when he desires to select a corresponding apparatus unit for operation or indication, and a two-

2

position disagreement key, such as DK1 for apparatus unit AU1, DK2 for apparatus unit AU2, etc., which respectively controls the operation of the corresponding disagreement lamps W1, W2, etc. of the corresponding group of indicating lamps. Each group of indicating lamps includes a red lamp, such as R1 for apparatus unit AU1, R2 for apparatus unit AU2, etc., which when lighted indicates that the corresponding apparatus unit is in its closed position; a green lamp, such as G1 for apparatus unit AU1, G2 for apparatus unit AU2, etc., which when lighted indicates that the corresponding apparatus unit is in its open position; a white lamp, such as W1 for apparatus unit AU1, W2 for apparatus unit AU2, etc., which when lighted indicates that the position of the corresponding apparatus unit does not correspond with the position of the associated disagreement key; and an amber lamp, such as A1 for apparatus unit AU1, A2 for apparatus unit AU2, etc., which when lighted indicates that the corresponding apparatus unit has been properly selected. Each group of disagreement keys and associated indicating lamps has associated therewith an individual indicating relay, such as IR1 for the group individual to apparatus unit AU1, IR2 for the group individual to apparatus unit AU2, etc., which determines by its position whether the associated red or green lamp is lighted and which cooperates with the associated disagreement key to determine whether the associated white lamp is lighted. The position of each indicating relay in turn is determined by the position of the corresponding apparatus unit in a manner which will be hereinafter described. As shown in Fig. 1, the indicating relays are shown in their deenergized position which is the position they occupy when their associated apparatus units at the remote station are in their open positions. The disagreement keys DK1 to DK5, inclusive, are also shown in the positions corresponding to the open positions of their respective apparatus units so that only the green lamps G1 to G5, inclusive, are lighted and all of the white and red lamps are not lighted. Each disagreement key is connected in such a manner that if it were in its other position under the conditions assumed, it would connect the associated white lamp and green lamp in series so that both lamps would be simultaneously lighted.

The equipment at the dispatcher's office also includes start lamp STL which is lighted when the supervisory equipment at both stations is in its normal-at-rest position and bell ringing relay BR which is normally energized and which is

arranged to be deenergized to effect the operation of suitable alarms such as bell AB and lamp AL when the operation of the supervisory equipment is initiated at the substation in response to one of the apparatus units thereat automatically changing its position.

When any one of the select keys is operated while the supervisory equipment is in its normal-at-rest position, a selection code of impulses corresponding to the operated select key is transmitted over line conductors L₁ and L₂ from the dispatcher's office to the substation to selectively energize and lock up at the substation the relay in a group of selection relays S'1 to S'5, inclusive, which is individual to the desired apparatus unit. The code which is transmitted to the substation is also registered at the dispatcher's office and operates a selection relay S₁ to S₅. Then a selection check code corresponding to the selected selection relay at the substation is transmitted over line conductors L₁ and L₂ from the substation to the dispatcher's office. If the two codes check properly, the selected apparatus unit may then be operated by the dispatcher operating master close key MCK which causes a closing control code of impulses to be transmitted over line conductors L₁ and L₂ from the dispatcher's office to the substation or master trip key MTK which causes a tripping control code of impulses to be transmitted over line conductors L₁ and L₂ from the dispatcher's office to the substation. If after selecting an apparatus unit for operation the dispatcher desires to check the position of the selected apparatus unit, he may do so by operating master check key CHK which causes an indication check code to be transmitted over line conductors L₁ and L₂ from the dispatcher's office to the substation. After each operation of the selected apparatus unit and after an indication check code has been transmitted, either a close indication code or a trip indication code, depending upon the position of the selected apparatus unit, is transmitted over line conductors L₁ and L₂ from the substation to the dispatcher's office.

In response to any apparatus unit at the substation automatically changing its position, a selection code of impulses corresponding to the changed apparatus unit is transmitted over line conductors L₁ and L₂ from the substation to the dispatcher's office to selectively energize at the dispatcher's office the selection relay individual to the changed apparatus unit and then a selection check code corresponding to the selected selection relay is transmitted over the line conductors from the dispatcher's office to the substation. If the selection check code checks with the transmitted selection code, an indication code corresponding to the new position of the changed apparatus unit is transmitted to the dispatcher's office to selectively operate at the dispatcher's office the indication relay individual to the changed apparatus unit so that the lamps individual to the operated apparatus unit will indicate the new position thereof.

In the particular embodiment of my invention shown in the drawing, all of the codes consist of four undirectional current impulses of the same length, but the codes differ from each other by the time elapsing, i. e., the pause, between the various impulses as will be seen from the following table of the codes:

Apparatus unit AU1—impulse; impulse; impulse; impulse.

- Apparatus unit AU2—impulse; impulse; impulse; pause; impulse.
 Apparatus unit AU3—impulse; impulse; pause; impulse; impulse.
 5 Apparatus unit AU4—impulse; pause; impulse; impulse; impulse.
 Apparatus unit AU5—impulse; pause; impulse; impulse; pause; impulse.
 Closing—impulse; pause; impulse; pause; impulse; pause; impulse.
 10 Tripping—impulse; impulse; pause; impulse; pause; impulse.
 Indication check—impulse; pause; impulse; pause; impulse; pause.
 15 Resetting—one impulse normally, but equipment will reset on any number of impulses other than four.

The selection and selection check codes are the same for each apparatus unit and so are the closing and close indication codes and the tripping and trip indication codes.

The pauses which occur between successive impulses and which are not indicated in the above table are materially shorter than the indicated pauses. In a practical embodiment of my invention, the length of pauses which occur between successive impulses and which are not indicated in the table are about the same length as the impulses, whereas the indicated pauses are about two and one-half times as long as the impulses.

The operation of any select key at the dispatcher's office effects the extinguishment of start lamp STL and the energization of start relay ST, which remains energized until the supervisory equipment is released, and the energization of sending control relay SC, which when energized effects the operation of a code transmitter comprising line impulse sender relay LS. When energized, relay LS connects the positive terminal of battery BAT to line conductor L₁ and the negative terminal of battery BAT to line conductor L₂ to cause a current impulse to be transmitted over the line conductors in series. This current impulse energizes at the dispatcher's office line impulse receiver relay LR which is connected across the line conductors so as to respond to any impulse transmitted over them and which when energized effects the energization of the associated auxiliary relay LX and interrupts the energizing circuit of impulse sender relay LS to terminate the current impulse. Therefore, relays LS, LX and LR are arranged to effect the transmission of a series of current impulses over line conductors L₁ and L₂.

At the substation, there is a similar group of relays L'S', L'X' and L'R' which is arranged to effect the transmission of a series of current impulses over line conductors L₁ and L₂, relay L'S' being arranged when energized to connect the positive terminal of battery B'A'T' to conductor L₁ and the negative terminal of battery B'A'T' to conductor L₂.

65 A group of four counting relays C₁ to C₄, inclusive, is provided at the dispatcher's office, and these relays are successively energized and locked up by the four impulses of the transmitted code. Transfer relay CT is provided for transferring the connections of relays C₁ to C₄, inclusive, so that they are selectively operated by the proper impulses of the code. A similar group of counting relays C'1 to C'4, inclusive, and transfer relay C'T' are operated at the substation by the 70 four impulses of each transmitted code.

For producing a relatively long pause between any two of the four impulses of a code transmitted from the dispatcher's office, pause relay PS is provided which when energized interrupts the energizing circuit of impulse sender relay LS. Pause relay PS is arranged to be energized in response to the energization of any one of the counting relays so that a pause may be produced between any two impulses. During the transmission of a selection code from the dispatcher's office, the circuit of pause relay PS is controlled by the particular select key that has been operated; during the transmission of a selection check code from the dispatcher's office, the circuit is controlled by the particular selection relay that has been energized by the selection code from the substation; and during the transmission of a control code, the circuit is controlled by the particular control key that has been operated. Pause relay PS is not energized during the transmission of a selection code effected by the operation of select key SK1 or during the transmission of a selection check code effected by selection relay S1 or S'1 because there is no pause in that code. Pause relay PS is energized in response to the energization of counting relay C3 so that a pause is produced between the third and fourth impulses of a selection code effected by the operation of select key SK2 and of a selection check code effected by selection relay S2 or S'2. Pause relay PS is energized in response to the energization of counting relay C2 so that a pause is produced between the second and third impulses of a selection code effected by the operation of select key SK3 and of a selection check code effected by selection relay S3 or S'3. Pause relay PS is energized in response to the energization of counting relay C1 so that a pause is produced between the first and second impulses of a selection code effected by the operation of select key SK4 and of a selection check code effected by selection relay S4 or S'4. Pause relay PS is energized in response to the energization of counting relays C1 and C3 so that a pause is produced between the first and second impulses and between the third and fourth impulses of a selection code effected by the operation of select key SK5 and of a selection check code effected by selection relay S5 or S'5. When master control key MTK is operated, pause relay PS is energized in response to the energization of counting relays C2 and C3 so that a pause is produced between the second and third control impulses and between the third and fourth control impulses. When master close key MCK is operated, pause relay PS is energized in response to the energization of counting relays C1 and C2 so that a pause is produced between the first and second control impulses and between the second and third control impulses. When the master check key CHK is operated, pause relay PS is energized in response to the energization of counting relays C1, C2 and C3 so that a pause is produced between the first and second impulses, between the second and third impulses and between the third and fourth impulses.

At the dispatcher's office, each pause effected during the transmission of a code causes a time delay drop-out code receiver relay PR, which is energized while relay LX is energized, to drop out. If the code is being transmitted from the dispatcher's office, the dropping out of relay PR also effects the deenergization of pause relay PS thereby terminating the pause and effecting

the reenergization of relay LS to transmit the next impulse of the code.

A similar pause relay P'S' is provided at the substation for producing a relatively long pause between any two of the impulses of a code transmitted from the substation. The circuit of pause relay P'S' is controlled during the transmission of a selection check code by the particular selection relay that has been selected at the substation by the selection code. During the transmission of a selection code transmitted from the substation, the circuit is controlled by the particular apparatus unit that has automatically changed its position, and during the transmission of an indication code, the circuit is controlled by the position of the selected apparatus unit at the time the indication code is being transmitted.

At the substation, each pause effected during the transmission of a code causes a similar time delay dropout code receiver relay P'R' to drop out and effect the deenergization of the associated pause relay P'S' if the code is being transmitted from the substation.

Three code pause register relays P12, P23, and P34 are selectively energized and locked up at the dispatcher's office in response to the long pauses between the impulses, relay P12 being energized and locked up during each pause produced between the first and second impulses, relay P23 being energized and locked up during each pause produced between the second and third impulses, and relay P34 being energized and locked up during each pause produced between the third and fourth impulses. Therefore, the energized condition of register relays P12, P23 and P34 at the termination of each code depends upon the code transmitted. None of these three register relays is energized during the transmission of the selection and of the selection check codes of apparatus unit AU1. Only relay P34 is energized during the transmission of the selection and of the selection check codes of apparatus unit AU2. Only relay P23 is energized during the transmission of the selection and of the selection check codes of apparatus unit AU3. Only relay P12 is energized during the transmission of the selection and of the selection check codes of apparatus unit AU4. Relays P12 and P34 are energized during the transmission of the selection and of the selection check codes of apparatus unit AU5. Relays P23 and P34 are energized during the transmission of the tripping and of the trip indication codes. Relays P12 and P23 are energized during the transmission of the closing and the close indication codes. Relays P12, P23 and P34 are energized during the transmission of the indication check code. A similar group of three pause register relays P'12, P'23 and P'34 are selectively energized and locked up at the substation in a similar manner by the pauses in the various transmitted codes.

The energization of counting relay C4 at the dispatcher's office in response to the fourth and last impulse of each code transmitted from the dispatcher's office interrupts the energizing circuit of relay LS so as to prevent it from being reenergized at the termination of the fourth impulse. The counting relay C'4 at the substation similarly prevents relay L'S' from being reenergized at the termination of the fourth impulse of each code transmitted from the substation. Consequently, after the termination of the fourth impulse of each code, time delay dropout relays

PR and P'R' are both deenergized for a sufficient length of time to drop out.

When relay PR drops out at the end of a selection code, it effects the energization and locking up of one of the group of five selection relays S₁ to S₅, inclusive, depending upon the selection code that has been transmitted. For example, relay S₁ is energized and locked up if the selection code for apparatus unit AU₁ is transmitted, relay S₂ is energized and locked up if the selection code for apparatus unit AU₂ is transmitted, etc. If the selection code is transmitted from the dispatcher's office, the selection relay is energized and locked up as soon as relay PR drops out, but if the selection code is transmitted from the substation, the selection relay is not energized until after relay PR has effected the dropping out of its associated time delay dropout operation delay relay OD. The energization of any selection relay S₁ to S₅, inclusive, effects the energization of counting chain reset relay CR which, in turn, effects the deenergization of sending control relay SC and of counting relays C₁ to C₄, inclusive, and any of the register relays at the dispatcher's office that are energized by the selection code. Relay CR also effects the energization and locking up of operation transfer relay T₁.

When relay P'R' drops out at the end of a selection code, it effects the energization and locking up of one of the group of selection relays S'₁ to S'₅, inclusive, depending upon the selection code that has been registered by relays P'₁₂, P'₂₃ and P'₃₄. For example, relay S'₁ is energized and locked up if the selection code of apparatus unit AU₁ has been transmitted, relay S'₂ is energized and locked up if the selection code of apparatus unit AU₂ has been transmitted, etc. If the selection code is transmitted from the substation to the dispatcher's office, the substation selection relay is energized as soon as relay P'R' drops out, but if the selection code is transmitted from the dispatcher's office, the substation selection relay is not energized until after relay P'R' has effected the dropping out of its associated time delay dropout operation delay relay O'D'. The energization of any selection relay S'₁ to S'₅, inclusive, effects the energization of counting chain reset relay C'R' which in turn deenergizes counting relays C'₁ to C'₄, inclusive, and any of the substation register relays that are energized by the selection code. Relay C'R' also effects the energization and locking up of operation transfer relay T'₁ at the substation. Relay T'₁ in turn completes a holding circuit for receiving control relay R'C', which is energized by relay C'₁ whenever a code is received at the substation from the dispatcher's office, and also completes an energizing circuit for sending control relay S'C' which effects the transmission of the selection check code corresponding to the selected substation selection relay from the substation to the dispatcher's office.

When substation relay P'R' drops out at the end of a selection check code, it effects the energization and locking up of code check relay C'H' if the proper selection check code has been transmitted. If the selection check code is transmitted from the substation, relay C'H' is energized as soon as relay P'R' drops out, but if the selection check code is transmitted from the dispatcher's office, relay C'H' is not energized until after relay P'R' has effected the dropping out of operation delay relay O'D'. Relay C'H' in turn effects the energization of counting chain reset relay C'R' to reset counting relays C'₁ to C'₄, inclusive, and

any of the substation register relays that are energized by the selection check code and to effect the energization and locking up of operation transfer relay T'2. When relay T'2 is energized, master indication relays I'C' and I'T' are selectively controlled by the position of the selected apparatus unit so that relay I'C' is energized if the selected apparatus unit is in its closed position and relay I'T' is energized if the selected apparatus unit is in its open position.

When relay PR at the dispatcher's office drops out at the end of a selection check code, it effects the energization and locking up of code check relay CH if the selection check code received at the dispatcher's office checks with the transmitted selection code. If the selection check code is transmitted from the dispatcher's office, relay CH is energized as soon as relay PR drops out, but if the selection check code is transmitted from the substation, relay CH is not energized until after relay PR has effected the dropping out of operation delay relay OD. Relay CH effects the lighting of the amber lamp corresponding to the selected apparatus unit, the energization of counting chain reset relay CR to reset the counting and register relays at the dispatcher's office, and also the energization and locking up of operation transfer relay T₂.

When relay PR at the dispatcher's office drops out at the end of a transmitted control code or a transmitted indication check code, the connections are such that relay PR effects the energization of counting chain reset relay CR to reset the counting and register relays at the dispatcher's office.

When relay P'R' at the substation drops out at the end of a transmitted control code, it effects the deenergization and dropping out of its associated operation delay relay O'D' which in turn effects the energization of master close relay M'C' if a closing code has been transmitted and the energization of master trip relay M'T' if a tripping code has been transmitted. When close relay M'C' is energized, it effects the closing of the selected apparatus unit, whereas when trip relay M'T' is energized, it effects the opening of the selected apparatus unit. The selected apparatus unit in changing its position causes its associated indication relay in a group of relays I'A'₁ to I'A'₅, inclusive, to become deenergized and change the energizations of relays I'C' and I'T' so that they are selectively energized in accordance with the new position of the selected apparatus unit. A circuit is also completed for counting chain reset relay C'R' in response to the operation of the selected apparatus unit to reset the substation counting and register relays.

When relay P'R' drops out at the end of a transmitted indication check code, it effects the deenergization and dropping out of its associated operation delay relay O'D' which in turn effects the energization of counting chain reset relay C'R' to reset the counting and register relays at the substation.

After the counting and register relays at the substation have been reset at the end of a control or indication check code, sending control relay S'C' is reenergized and locked up to effect the transmission of an indication code corresponding to the position of the selected apparatus unit.

When substation relay P'R' drops out at the end of an indication code, it effects the reenergization of the indication relay associated with the selected apparatus unit and also effects the

energization of counting chain reset relay C'R' to reset the substation counting and register relays.

When relay PR at the dispatcher's office drops out at the end of the transmission of an indication code, it effects the deenergization and dropping out of its associated operation delay relay OD which in turn effects the energization of master indication close relay MC if a close indication code has been transmitted and the energization of master indication trip relay MT if a trip indication code has been transmitted. When close relay MC is energized, it effects the energization of the indication relay in relay group IR1 to IR5, inclusive, which is individual to the selected apparatus unit so that the indicating lamps individual to the selected apparatus unit are lighted to indicate it is in its closed position. When trip relay MT is energized, it effects the deenergization of the indication relay of relay group IR1 to IR5, inclusive, which is individual to the selected apparatus unit so that the indicating lamps individual to the selected apparatus unit are lighted to indicate that it is in its open position.

The operation of an indication relay in relay group IR1 to IR5, inclusive, in response to an indication code effects the energization of counting chain reset relay CR to reset the counting and register relays at the dispatcher's office.

For restoring the supervisory equipment after a selection has been made, lockout relay LO at the dispatcher's office is arranged to be energized in response to an operated select key being restored to its normal position. Lockout relay LO is also arranged to be energized in response to the operation of emergency reset key EMK by the dispatcher. Lockout relay LO when energized is arranged to effect the transmission of a single reset impulse over line conductors L1 and L2. This single reset impulse causes release relay RL at the dispatcher's office to operate and reset the apparatus unit thereat to its normal-at-rest position and to operate release relay R'L' at the substation to reset the apparatus unit thereat to its normal-at-rest position.

At the substation, start relay S'T' is arranged to be energized and locked up in response to any one of the apparatus units thereat changing its position and effecting the deenergization of its associated indication relay while the supervisory equipment is in its normal-at-rest position. When energized, start relay S'T' causes a selection code corresponding to the apparatus unit which has changed its position to be transmitted from the substation to the dispatcher's office. This selection code effects at the substation and at the dispatcher's office the energization and locking up of the selection relays individual to the apparatus unit which has changed its position.

The first impulse of the selection code received at the dispatcher's office from the substation also effects the deenergization of bell relay BR so that circuits are completed for alarm bell AB and alarm lamp AL and the circuit for start lamp STL is interrupted. A selection check code corresponding to the selected selection relay at the dispatcher's office is then transmitted to the substation, and if this selection check code agrees with the transmitted selection code, an indication code corresponding to the position of the operated apparatus unit is then transmitted from the substation to the dispatcher's office to selectively operate at the dispatcher's office the indication relays individual to the operated apparatus unit so that the associated lamps will indicate the new

position occupied by the operated apparatus unit. Also, the indication code effects at the substation the energization and locking up of the indication relay individual to the operated apparatus unit.

5 At the termination of the indication code, a single reset impulse is transmitted from the dispatcher's office to the substation to restore the supervisory apparatus at the two stations to its normal-at-rest position.

10 Relay BR will remain deenergized with the bell ringing and alarm lamp AL lighted until the dispatcher presses emergency reset key EMK. Key EMK energizes relay BR, thereby silencing the bell, extinguishing alarm lamp AL and lighting start lamp STL.

15 The unit whose indication was changed by the automatic operation will be marked by the white disagreement lamp until acknowledged by the dispatcher turning the corresponding disagreement key to the new position.

20 A detailed description of the operation of the embodiment of my invention shown in the drawings is as follows: When the equipment is not in use, each group of lamps is lighted to indicate the

25 position of the corresponding apparatus unit. For the purpose of this description, it will be assumed that each of the apparatus units in the substation is in its open position so that its associated green lamp in the dispatcher's office is lighted through

30 a circuit including contacts b of the associated indicating relay and contacts d of the associated disagreement key. For example, the circuit of green lamp G2 includes contacts b of indicating relay IR2 and contacts d of disagreement key

35 DK2.

40 When the supervisory equipment at both stations is in its normal-at-rest position, bell ringing relay BR and operation delay relay OD at the dispatcher's office are energized, and operation delay relay O'D' and all of the I'A' relays at the substation are energized. The circuit of bell ringing relay BR includes resistor R1, conductor 221 and contacts a of relay BR. The energizing circuit of operation delay relay OD at the

45 dispatcher's office includes contacts f of relay C1. The circuit of operation delay relay O'D' at the substation includes contacts d of relay C'1. Since each of the apparatus units is assumed to be in its open position, the energizing circuit of each

50 of the associated indicating relays at the substation is completed through auxiliary contacts b of the apparatus unit and the lower winding and contacts a of the associated indicating relay. For example, the circuit of indicating relay I'A'2 is

55 completed through the lower winding of this relay, contacts a of relay I'A'2 and auxiliary contacts b of apparatus unit AU2.

When the equipment is in its normal-at-rest position, a circuit is also completed for start lamp

60 STL through contacts b of relay LX, contacts d of relay C1, conductor 300, contacts b of select key SK1, contacts b of select key SK2, contacts b of select key SK3, contacts b of select key SK4, contacts b of select key SK5, conductor 100, contacts f of start relay ST, conductor 200 and contacts c of relay BR.

65 It will now be assumed that the dispatcher desires to select and operate apparatus unit AU2 at the substation. After first observing that start lamp STL is lighted, the operator moves select key SK2 from the position shown in the drawing to its other position and then moves disagreement key DK2 to its other position. The opening of contacts d and the closing of contacts c of dis-

70 agreement key DK2 effect the connection of white

75 contacts d and the closing of contacts c of dis-

lamp W2 in series with green lamp G2 so that both of these lamps are lighted.

The opening of contacts *b* of select key SK2 opens the above traced circuit for start lamp STL. The closing of contacts *a* of select key SK2 completes an energizing circuit for start relay ST through conductor 223, contacts *h* of relay T1, contacts *d* of relay RC, conductor 281, contacts *a* of select key SK2, contacts *b* of select key SK1, conductor 300, contacts *d* of relay C1 and contacts *b* of relay LX. By closing its contacts *c*, start relay ST completes a locking circuit for itself through contacts *h* of relay RL. The closing of contacts *a* of start relay ST completes an energizing circuit for sending relay SC through conductor 301, contacts *a* of start relay ST, conductor 282, contacts *f* of relay T1, contacts *f* of relay T2, contacts *b* of relay C1, conductor 302 and contacts *b* of relay CR. The closing of contacts *e* of relay SC completes a locking circuit for this relay through conductor 302 and contacts *b* of relay CR.

The closing of contacts *c* of relay SC completes an energizing circuit for line impulse sender relay LS through contacts *b* of relay PS, contacts *d* of relay LX, conductor 303, contacts *b* of relay RL, conductor 304, contacts *c* of relay SC, conductor 305, contacts *d* of relay CR, conductor 283 and contacts *f* of relay C4. The closing of contacts *a* of relay LS connects the positive terminal of battery BAT to line conductor L1 and the closing of contacts *c* of relay LS connects the negative terminal of battery BAT to line conductor L2 so that a positive impulse is transmitted over the line conductors.

At the dispatcher's office, this impulse picks up line relay LR, which by closing its contacts *a* completes an energizing circuit for auxiliary line relay LX. The closing of contacts *a* of relay LX completes an energizing circuit for code pause receiver relay PR. The closing of contacts *a* of relay PR completes a holding circuit for relay OD so that this relay does not become deenergized when relay C1 opens its contact *f*. The closing of contacts *a* of relay LX also completes an energizing circuit for counting relay C1 through contacts *b* of relay CT and contacts *b* of relay C2. The closing of contacts *a* of relay C1 completes a locking circuit for this relay through conductor 302 and contacts *b* of relay CR and a locking circuit for relay PR through contacts *b* of relay CT, contacts *b* of relay C2, contacts *a* of relay C1, conductor 302 and contacts *b* of relay CR.

The opening of contacts *d* of relay LX interrupts the heretofore described circuit for line impulse sender relay LS so that it opens its contacts *a* and *c* to remove the impulse from line conductors L1 and L2 thereby effecting the successive deenergization of the relays LR and LX. The closing of contacts *b* of relay LX completes an energizing circuit for counting chain transfer relay CT through contacts *e* of relay C1, contacts *f* of relay C2 and contacts *h* of relay C4. The closing of contacts *c* of relay CT completes a shunt circuit around contacts *b* of relay LX so as to complete a locking circuit for relay CT. The opening of contacts *b* of relay CT interrupts the locking circuit of relay PR, but due to the fact that this relay is a time delayed dropout relay, it remains in its energized position for a predetermined time after its energizing circuit is interrupted.

The closing of contacts *d* of the relay LX re-establishes the heretofore described energizing circuit for relay LS so that it again connects line

conductors L1 and L2 to the battery BAT so as to cause another impulse to be transmitted over these line conductors.

The second impulse to be transmitted over line conductors L1 and L2 effects the energization of relays LR and LX, and the closing of contacts *a* of relay LX reenergizes relay PR before it has had time to be restored to its normally deenergized position. The closing of contacts *a* of relay LX also completes an energizing circuit for chain relay C2 through contacts *b* of relay C3 and contacts *a* of relay CT. The closing of contacts *a* of relay C2 completes a locking circuit for this relay through conductor 302 and contacts *b* of relay CR and also a locking circuit for relay PR through contacts *a* of relay CT, contacts *b* of relay C3, contacts *a* of relay C2, conductor 302 and contacts *b* of relay CR. The opening of contacts *d* of relay LX again interrupts the energizing circuit of relay LS so as to terminate the impulse being sent over line conductors L1 and L2 and deenergize relays LR and LX. The opening of contacts *c* of relay LX, which contacts are connected in parallel with the series connected contacts *h* of relay C4 and *f* of relay C2 in the heretofore described energizing circuit of relay CT, interrupts the holding circuit of relay CT so that this relay becomes deenergized. The opening of contacts *a* of relay CT interrupts the holding circuit of relay PR.

The closing of contacts *d* of relay LX again re-establishes the energizing circuit of relay LS so that a third impulse is transmitted over line conductors L1 and L2, and this third impulse effects the energization of relays LR and LX in the same manner as the two previous impulses. The closing of contacts *a* of relay LX again reestablishes the energizing circuit of relay PR before this relay can drop out and also completes an energizing circuit for counting relay C3 through contacts *d* of relay C4, contacts *c* of relay C2 and contacts *b* of relay CT. The closing of contacts *a* of relay C3 completes a locking circuit for this relay through conductor 302 and contacts *b* of relay CR and also completes a locking circuit for relay PR through contacts *b* of relay CT, contacts *c* of relay C2, contacts *d* of relay C4, contacts *a* of relay C3, conductor 302 and contacts *b* of relay CR. The closing of contacts *f* of relay C3 completes an energizing circuit for code pause sender relay PS through conductor 306, contacts *b* of relay LO, conductor 284, contacts *c* of relay PR, conductor 307, contacts *f* of relay C3, contacts *b* of relay CH, conductor 309, contacts *f* of relay ST, conductor 285, contacts *c* of select key SK2, conductor 183, contacts *f* of relay P23, conductor 286, contacts *f* of relay P12, conductor 310, contacts *a* of relay OD, contacts *b* of relay C4, contacts *g* of relay C1, conductor 302 and contacts *b* of relay CR.

The opening of contacts *d* of relay LX again interrupts the energizing circuit of relay LS so as to terminate the third impulse and cause relays LR and LX to become deenergized. The closing of contacts *d* of relay LX does not re-establish the heretofore described energizing circuit for relay LS because this circuit is now open at contacts *b* of relay PS. The closing of contacts *b* of relay LX completes an energizing circuit for relay CT through contacts *h* of relay C4, contacts *g* of relay C3 and contacts *e* of relay C1. The closing of contacts *c* of relay CT shunts contacts *b* of relay LX so as to complete a locking circuit for relay CT. The opening of contacts *b* of relay CT inter-

13

rupts the locking circuit of relay PR, and since the circuit of relay LS is still open at contacts *b* of relay PS, relay PR remains deenergized for a sufficient time to drop out and close its contacts *d*, thereby completing an energizing circuit for code register relay P34 through conductor 207, contacts *e* of relay C3, contacts *b* of relay PR, contacts *a* of relay OD, contacts *b* of relay C4, contacts *g* of relay C1, conductor 302 and contacts *b* of relay CR. The closing of contacts *a* of relay P34 completes a locking circuit for this relay through conductor 302 and contacts *b* of relay CR.

The opening of contacts *c* of relay PR interrupts the heretofore described energizing circuit for relay PS so that it closes its contacts *b* and reestablishes the heretofore described energizing circuit for relay LS so that a fourth impulse is transmitted over line conductors L1 and L2, and this fourth impulse effects the energization of relays LR and LX in the same manner as the three previous impulses. The closing of contacts *a* of relay LX again reestablishes the energization of relay PR so that it is again picked up. The closing of contacts *a* of relay LX also completes an energizing circuit for counting relay C4 through contacts *c* of relay C3 and contacts *a* of relay CT. The closing of contacts *a* of relay C4 completes a locking circuit for this relay through conductor 302 and contacts *b* of relay CR and also a locking circuit for relay PR through contacts *a* of relay CT, contacts *c* of relay C3, contacts *a* of relay C4, conductor 302 and contacts *b* of relay CR.

The opening of contacts *d* of relay LX again interrupts the energizing circuit of relay LS so as to terminate the fourth impulse and cause relays LR and LX to become deenergized. The opening of contacts *c* of relay LX, which contacts are connected in parallel with the series connected contacts *h* of relay C4 and contacts *g* of relay C3 in the heretofore described energizing circuit of relay CT, interrupts the circuit of relay CT so that this relay becomes deenergized and at its contacts *a* interrupts the locking circuit of relay PR. The closing of contacts *d* of relay LX does not reestablish the heretofore described energizing circuit of relay LS because this circuit is now open at contacts *f* of relay C4. Consequently, contacts *a* of relay LX remain open long enough to allow relay PR to drop out and complete an energizing circuit for selection point relay S2 through conductor 104, contacts *e* of relay P34, contacts *d* of relay P23, contacts *b* of relay P12, conductor 208, contacts *b* of relay T2, contacts *i* of relay C4, contacts *a* of relay SC, contacts *d* of relay PR, contacts *j* of relay T1, conductor 311 and contacts *j* of relay RL.

The closing of contacts *c* of relay S2 completes a locking circuit for this relay through conductor 311 and contacts *j* of relay RL. The closing of contacts *i* of relay S2 completes an energizing circuit for counting chain reset relay CR through contacts *f* of relay IR2, conductor 105, contacts *b* of relay MT, conductor 209, contacts *d* of relay T1 and conductor 320. The opening of contacts *b* of relay CR interrupts the heretofore described locking circuits for relays C1, C2, C3, C4, P34 and SC so that these relays are restored to their normal deenergized positions. The closing of contacts *f* of relay C1 reestablishes the heretofore described energizing circuit for relay OD. The closing of contacts *a* of relay CR completes an energizing circuit for relay T1 through contacts *f* of relay RL, conductor 210 and contacts *b*

14

of relay CH. The closing of contacts *a* of relay T1 completes a locking circuit for this relay through conductor 311 and contacts *j* of relay RL. The opening of contacts *d* of relay T1 interrupts the heretofore described energizing circuit of relay CR. Therefore, at the end of the selection code, relays ST, T1, S2, OD and BR at the dispatcher's office are energized.

While the selection impulses are effecting the heretofore described operations at the dispatcher's office, they are also effecting the following operations at the substation: The first impulse transmitted over line conductors L1 and L2 effects the energization of relay L'R', which by closing its contacts *a* completes an energizing circuit for relay L'X'. The closing of contacts *a* of relay L'X' completes an energizing circuit for code pause receiver relay P'R'. The closing of contacts *a* of relay P'R' completes a holding circuit for relay O'D' so that this relay does not become deenergized when relay C'1 opens its contacts *d*. The closing of contacts *a* of relay L'X' also completes an energizing circuit for counting relay C'1 through contacts *b* of relay C'2 and contacts *b* of relay C'T'. The closing of contacts *a* of relay C'1 completes a locking circuit for this relay through conductor 400 and contacts *b* of relay C'R' and also a locking circuit for relay P'R' through contacts *b* of relay C'T', contacts *b* of relay C'2, contacts *a* of relay C'1, conductor 400 and contacts *b* of relay C'R'.

At the termination of the first impulse, relay L'R' opens its contacts *a* and effects the deenergization of relay L'X'. The closing of contacts *d* of relay L'X' completes an energizing circuit for relay C'T' through contacts *k* of relay C'1, contacts *f* of relay C'2 and contacts *h* of relay C'4. The closing of contacts *c* of relay C'T' completes a shunt circuit around contacts *d* of relay L'X' so as to complete a locking circuit for relay C'T'. The closing of contacts *e* of relay C'T' completes an energizing circuit for relay R'C' through conductor 500, contacts *e* of relay C'T', conductor 401, contacts *b* of relay S'C', conductor 402 and contacts *e* of relay C'1. The closing of contacts *i* of relay R'C' completes a shunt circuit around contacts *e* of relay C'T' in the energizing circuit of relay R'C'. The opening of contacts *b* of relay C'T' interrupts the heretofore described locking circuit of relay P'R', but due to the fact that this relay is a time delayed dropout relay, it remains in its energized position for a predetermined time after its energizing circuit is interrupted.

The second impulse of the selection code effects the energization of the relays L'R' and L'X' in the same manner as the first impulse, and the closing of contacts *a* of relay L'X' reenergizes relay P'R' before it has had time to be restored to its normally deenergized position. The closing of contacts *a* of relay L'X' also completes an energizing circuit for chain relay C'2 through contacts *d* of relay C'3 and contacts *a* of relay C'T'. The closing of contacts *a* of relay C'2 completes a locking circuit for this relay through conductor 400 and contacts *b* of relay C'R' and also a locking circuit for relay P'R' through contacts *a* of relay C'T', contacts *a* of relay C'2, conductor 400 and contacts *b* of relay C'R'.

At the termination of the second impulse, relays L'R' and L'X' are again deenergized and the opening of contacts *c* of relay L'X', which contacts are connected in parallel with the series connected contacts *f* of relay C'2 and contacts *h* of relay C'4 in the heretofore described ener-

15

gizing circuit of relay C'T', interrupts the holding circuit of this relay so that it becomes deenergized. The opening of contacts *a* of relay C'T' interrupts the heretofore described locking circuit for relay P'R'.

When the third impulse is transmitted over line conductors L₁ and L₂, relays L'R' and L'X' are again energized. The closing of contacts *a* of L'X' reestablishes the energizing circuit of relay P'R' before this relay can drop out and also completes an energizing circuit for counting relay C'3 through contacts *d* of relay C'4, contacts *c* of relay C'2 and contacts *b* of relay C'T'. The closing of contacts *a* of relay C'3 completes a locking circuit for this relay through conductor 400 and contacts *b* of relay C'R' and also completes a locking circuit for relay P'R' through contacts *b* of relay C'T', contacts *c* of relay C'2, contacts *d* of relay C'4, contacts *a* of relay C'3, conductor 400 and contacts *b* of relay C'R'.

At the end of the third impulse, relays L'R' and L'X' are again deenergized, and the closing of contacts *d* of relay L'X' reestablishes another circuit for relay C'T' through contacts *k* of relay C'4, contacts *g* of relay C'3 and contacts *h* of relay C'4. The closing of contacts *c* of relay C'T' reestablishes the holding circuit for this relay around contacts *d* of relay L'X', and the opening of contacts *b* of relay C'T' interrupts the locking circuit of relay P'R'.

Since between the third and fourth impulses there is a long pause due to the energization of code pause sender relay PS at the dispatcher's office, contacts *a* of relay L'X' remain open for a sufficient length of time to allow time relay P'R' to drop out. The closing of contacts *b* of relay P'R' completes an energizing circuit for relay P'34 through conductor 501, contacts *e* of relay C'3, contacts *b* of relay P'R', contacts *b* of relay L'O', contacts *a* of relay O'D', contacts *b* of relay C'4, contacts *c* of relay C1, conductor 400 and contacts *b* of relay C'R'. The closing of contacts *a* of relay P'34 completes a locking circuit for this relay through conductor 400 and contacts *b* of relay C'R'.

The fourth impulse effects the energization of the relays L'R' and L'X' in the same manner as the previous impulses, and the closing of contacts *a* of relay L'X' reestablishes the energizing circuit of relay P'R' so that this relay again picks up. The closing of contacts *a* of relay L'X' also completes an energizing circuit for counting relay C'4 through contacts *c* of relay C'3 and contacts *a* of relay C'T'. The closing of contacts *a* of relay C'4 completes a locking circuit for this relay through conductor 400 and contacts *b* of relay C'R' and also a locking circuit for relay P'R' through contacts *a* of relay C'T', contacts *c* of relay C'3, contacts *a* of relay C'4, conductor 400 and contacts *b* of relay C'R'.

At the termination of the fourth impulse, relays L'R' and L'X' are again deenergized. The opening of contacts *c* of relay L'X', which contacts are connected in parallel with the series connected contacts *g* of relay C'3 and contacts *h* of relay C'4 in the heretofore described energizing circuit for relay C'T', interrupts the holding circuit of this relay so that it becomes deenergized. A predetermined time after contacts *a* of relay C'T' are opened, relay P'R' drops out and opens its contacts *a* in the holding circuit of relay O'D'. After being deenergized for a predetermined time interval, relay O'D' also drops out and by closing its contacts *f* completes an energizing circuit for relay S'2 through conductor

16

888, contacts *e* of relay P'34, contacts *d* of relay P'23, contacts *b* of relay P'12, conductor 502, contacts *b* of relay T'2, contacts *i* of relay C'4, contacts *f* of relay O'D', contacts *d* of relay P'R', conductor 404, contacts *h* of relay T'1, conductor 503 and contacts *h* of relay R'L'. The closing of contacts *g* of relay S'2 completes a locking circuit for this relay through conductor 403, contacts *f* of relay L'O', conductor 503 and contacts *h* of relay R'L'. The closing of contacts *e* of relay S'2 completes an energizing circuit for relays I'C' and I'T' in series through conductor 603. The closing of contacts *a* of relay I'T' completes an energizing circuit for relay C'R' through contact *b* of relay R'L', conductor 426, contacts *a* of relay I'T', contacts *b* of relay T'1 and conductor 505. The opening of contacts *b* of relay C'R' interrupts the heretofore described holding circuits of the relays C'1 to C'4, inclusive, and P'34. The closing of contacts *d* of relay C'1 reestablishes the original energizing circuit for relay O'D'. The closing of contacts *a* of relay C'R' completes an energizing circuit for relay T'1 through conductor 506, contacts *d* of relay R'L', contacts *d* of relay L'O', contacts *f* of relay C'H' and conductor 407. The closing of contacts *c* of relay T'1 completes a locking circuit for itself through conductor 403, contacts *f* of relay L'O', conductor 503 and contacts *h* of relay R'L'. The closing of contacts *g* of relay T'1 completes a holding circuit for relay R'C' through contacts *h* of relay R'L', conductor 503, contact *g* of relay T'1, conductor 402, contacts *b* of relay S'C', conductor 401 and contacts *i* of relay R'C'. The opening of contacts *b* of relay T'1 interrupts the heretofore described energizing circuit of relay C'R'.

Therefore, at the end of the selection code, relays R'C', T'1, S'2, I'C', I'T', O'D', and I'A'1 to I'A'5, inclusive, are energized, and the substation is now ready to transmit a selection check code to the dispatcher's office. This selection check code is the same as the selection code; namely, four positive impulses with a pause between the third and fourth impulses.

The closing of contacts *a* of relay T'1 completes an energizing circuit for the relay S'C' through contacts *h* of relay L'O', conductor 408, contacts *a* of relay R'C', contacts *a* of relay T'1, conductor 509, contacts *d* of relay T'2, contacts *b* of relay C'1, conductor 400 and contacts *b* of relay C'R'. The closing of contacts *c* of relay S'C' completes a locking circuit for this relay through contacts *h* of relay L'O', conductor 408, contacts *c* of relay S'C', conductor 400 and contacts *b* of relay C'R'. The opening of contacts *b* of relay S'C' interrupts the heretofore described holding circuit for relay R'C'. The closing of contacts *e* of relay S'C' completes an energizing circuit for relay L'S' through contacts *b* of relay P'S', contacts *b* of relay L'X', conductor 406, contacts *e* of relay S'C', contacts *f* of relay C'4, conductor 410 and contacts *d* of relay C'R'. The closing of contacts *a* of relay L'S' connects the positive terminal of battery B'A'T' to line conductor L₁, and the closing of contacts *c* of relay L'S' connects the negative terminal of battery B'A'T' to line conductor L₂ so that the first positive impulse of the selection check code is transmitted over the line conductors.

At the substation, this impulse picks up relay L'R', which by closing its contacts *a* completes the energizing circuit of relay L'X'. The closing of contacts *a* of relay L'X' completes

the energizing circuit for relay P'R' which in turn reestablishes the holding circuit for relay O'D' so that this relay does not become deenergized when relay C'1 opens its contacts *d*. The closing of contacts *a* of relay L'S' also completes the heretofore described energizing circuit for counting relay C'1, which by closing its contacts *a* completes the heretofore described locking circuits for itself and for relay P'R'.

The opening of contacts *b* of relay L'X' interrupts the heretofore described circuit for relay L'S' so that it opens its contacts *a* and *c* to remove the impulse from line conductors L1 and L2, thereby effecting the deenergization of relays L'R' and L'X'. The closing of contacts *d* of relay L'X' completes the energizing circuit for relay C'T' through contacts *k* of relay C'1, contacts *f* of relay C'2 and contacts *h* of relay C'4. The closing of contacts *c* of relay C'T' completes a shunt circuit around contacts *d* of relay L'X' in the energizing circuit for relay C'T'. The opening of contacts *b* of relay C'T' interrupts the locking circuit for relay P'R', but due to the fact that this is a time delay dropout relay, it remains in its energized position for a predetermined time after its energizing circuit is interrupted.

The closing of contacts *b* of relay L'X' reestablishes the energizing circuit of relay L'S' so that it again connects line conductors L1 and L2 to battery B'A'T' and causes the second impulse of the selection check code to be transmitted over these line conductors.

This second impulse effects the energization of relays L'R' and L'X', and the closing of contacts *a* of relay L'X' reenergizes relay P'R' before it has had time to be restored to its normally deenergized position. The closing of contacts *a* of relay L'X' also completes the energizing circuit for relay C'2 through contacts *d* of relay C'3 and contacts *a* of relay C'T'. The closing of contacts *a* of relay C'2 completes the heretofore described locking circuits for this relay and relay P'R' through conductor 488 and contacts *b* of relay C'R'. The opening of contacts *b* of relay L'X' again interrupts the energizing circuit of relay L'S' so as to terminate the second impulse and effect the deenergization of relays L'R' and L'X'. The opening of contacts *c* of relay L'X', which contacts are connected in parallel with series connected contacts *f* of relay C'2 and contacts *h* of relay C'4 in the heretofore described energizing circuit of relay C'T', interrupts the holding circuit of this relay so that it becomes deenergized. The opening of contacts *a* of relay C'T' interrupts the holding circuit of relay P'R'.

The closing of contacts *b* of relay L'X' again reestablishes the energizing circuit of relay L'S' so that the third impulse of the selection check code is transmitted over line conductors L1 and L2, and this third impulse effects the energization of relays L'R' and L'X' in the same manner as the two previous impulses. The closing of contacts *a* of relay L'X' again reestablishes the energizing circuit of relay P'R' before this relay can drop out and also completes the energizing circuit for relay C'3 through contacts *d* of relay C'4, contacts *c* of relay C'2 and contacts *b* of relay C'T'. The closing of contacts *a* of relay C'3 completes the heretofore described locking circuit for this relay and relay P'R' through conductor 488 and contacts *b* of relay C'R'.

The closing of contacts *f* of relay C'3 completes an energizing circuit for relay P'S' through contacts *c* of relay P'R', contacts *f* of relay C'3, con-

tacts *b* of relay C'H', conductor 411, contacts *m* of relay S'2, conductor 488, contacts *e* of relay S'C', contacts *f* of relay C'4, conductor 410 and contacts *d* of relay C'R'.

The opening of contacts *b* of relay L'X' interrupts the energizing circuit of relay L'S' so as to terminate the third impulse and causes relays L'R' and L'X' to become deenergized. The closing of contacts *b* of relay L'X' does not reestablish the heretofore described energizing circuit of relay L'S' because this circuit is now open at contacts *b* of relay P'S'. The closing of contacts *d* of relay L'X' completes an energizing circuit for relay C'T' through contacts *k* of relay C'1, contacts *g* of relay C'3 and contacts *h* of relay C'4. The closing of contacts *c* of relay C'T' shunts contacts *d* of relay L'X' so as to complete a locking circuit for relay C'T'.

The opening of contacts *b* of relay C'T' deenergizes the relay P'R', which after being deenergized for a predetermined time opens its contacts *a* and interrupts the holding circuit for relay O'D'. Before time relay O'D' drops out, a circuit is completed for relay P'34 through conductor 581, contacts *e* of relay C'3, contacts *b* of relay P'R', contacts *b* of relay L'O' and contacts *a* of relay O'D', contacts *b* of relay C'4, contacts *c* of relay C'1, conductor 488 and contacts *b* of relay C'R'. The closing of contacts *a* of relay P'34 completes a locking circuit for this relay through conductor 488 and contacts *b* of relay C'R'. The opening of contacts *c* of relay P'R' interrupts the heretofore described energizing circuit of relay P'S' so that the closing of its contacts *b* reestablishes the heretofore described energizing circuit for relay L'S'.

The energization of relay L'S' causes the fourth impulse of the selection check code to be transmitted over line conductors L1 and L2, and this fourth impulse effects the energization of relays L'R' and L'X' in the same manner as the three previous impulses. The closing of contacts *a* of relay L'X' again reestablishes the energization of relay P'R' so that it again picks up and reenergizes relay O'D' before it drops out. The closing of contacts *a* of relay L'X' also completes an energizing circuit for counting relay C'4 through contacts *c* of relay C'3 and contacts *a* of relay C'T'. The closing of contacts *a* of relay C'4 completes the heretofore described locking circuits for this relay and relay P'R' through conductor 488 and contacts *b* of relay C'R'.

The opening of contacts *b* of relay L'X' again interrupts the circuit of relay L'S' so as to terminate the fourth impulse and cause relays L'R' and L'X' to become deenergized. The opening of contacts *c* of relay L'X', which contacts are connected in parallel with the series connected contacts *g* of relay C'3 and contacts *h* of relay C'4 in the heretofore described energizing circuit of relay C'T', interrupts the circuit of relay C'T' so that this relay becomes deenergized, and by opening its contacts *a*, deenergizes relay P'R'. The closing of contacts *b* of relay L'X' does not reestablish the heretofore described energizing circuit of relay L'S' because this circuit is now open at contacts *f* of relay C'4. Consequently, contacts *a* of relay L'X' remain open long enough to allow relay P'R' to drop out. If the proper check code has been transmitted, an energizing circuit for code check relay C'H' is completed through conductor 412, contacts *e* of relay T'1, conductor 484, contacts *d* of relay P'R', contacts *a* of relay S'C', contacts *f* of relay C'4, contacts *b* of relay T'2, conductor 582, contacts *b* of relay

P'12, contacts *d* of relay P'23, contacts *e* of relay P'34, conductor 808, contacts *g* of relay S'2, conductor 403, contacts *f* of relay L'O', conductor 503 and contacts *h* of relay R'L'.

The closing of contacts *k* of relay C'H' completes a locking circuit for this relay through conductor 403, contacts *f* of relay L'O', conductor 503 and contacts *h* of relay R'L'. The closing of contacts *g* of relay C'H' completes an energizing circuit for relay C'R' through contacts *f* of relay T'2 and conductor 505. The opening of contacts *b* of relay C'R' interrupts the heretofore described locking circuits for relays C'1 to C'4, inclusive P'34 and S'C'. The closing of contacts *d* of relay C'1 reestablishes the energizing circuit for relay O'D'.

The closing of contacts *a* of relay C'R' completes an energizing circuit for relay T'2 through conductor 506, contacts *d* of relay R'L', contacts *d* of relay L'O' and contacts *f* of relay C'H'. By closing its contacts *g*, relay T'2 completes a locking circuit for this relay through conductor 403, contacts *f* of relay L'O', conductor 503 and contacts *h* of relay R'L'. The opening of contacts *g* of relay T'2 interrupts the heretofore described energizing circuit for relay C'R', and the closing of contacts *e* of relay T'2 completes a shunt circuit around the winding of relay I'C' through conductor 511, contacts *e* of relay T'2, conductor 413, contacts *a* of relay S'2 and contacts *b* of apparatus unit AU2. Consequently relay I'C' drops out and relay I'T' remains energized.

At the termination of the selection check code, relays S'2, C'H', T'1, T'2, I'T', O'D', and I'A'1 to I'A'5, inclusive, are energized at the substation.

The four impulses of the selection check code effect the same operation of the relays LR, LX, C1 to C4, inclusive, CT, PR, OD and P'34 at the dispatcher's office as the impulses of the selection code did, except that the energization of relay CT at the end of the first impulse of a selection check code completes an energizing circuit for relay RC through contacts *e* of relay CT, contacts *b* of relay SC, conductor 311 and contacts *f* of relay RL. This circuit for relay RC was not completed during the transmission of the selection code because the contacts *b* of relay SC were then open. By closing its contact *i*, relay RC completes a locking circuit for itself by shunting contacts *e* of relay CT.

At the termination of the fourth impulse of the selection check code, time delay relays PR and OD successively become deenergized and drop out. If the correct selection code is received by the apparatus at the dispatcher's office, the closing of contacts *b* of relay OD completes an energizing circuit for relay CH through contacts *e* of relay T1, contacts *d* of relay PR, contacts *b* of relay OD, contacts *i* of relay C4, contacts *b* of relay T2, conductor 208, contacts *b* of relay P'12, contacts *d* of relay P'23, contacts *e* of relay P'34, conductor 104, contacts *c* of relay S2, conductor 311 and contacts *f* of relay RL. The closing of contacts *i* of relay CH completes a locking circuit for this relay through conductor 311 and contacts *f* of relay RL. The closing of contacts *c* of relay CH completes a circuit for amber lamp A2 through conductor 312 and contacts *a* of relay S2. The lighting of amber lamp A2 informs the dispatcher that apparatus unit AU2 at the substation has been properly selected. The closing of contacts *g* of relay CH completes an energizing circuit for relay CR through contacts *d* of relay T2, contacts *a* of relay T1 and conductor 320. The open-

ing of contacts *b* of relay CR interrupts the locking circuits of relays C1 to C4, inclusive, and P'34 so that these relays become deenergized. The closing of contacts *f* of relay C1 reestablishes the energizing circuit of relay OD. The closing of contacts *a* of relay CR completes an energizing circuit for relay T2 through contacts *f* of relay RL, conductor 210 and contacts *k* of relay CH. The closing of contacts *e* of relay T2 completes a locking circuit for this relay through conductor 311 and contacts *f* of relay RL. The opening of contacts *d* of relay T2 interrupts the heretofore described circuit for relay CR.

Therefore, at the termination of the selection check code, relays ST, S2, CH, T1, T2, RC, OD and BR are energized at the dispatcher's office.

It will now be assumed that the dispatcher desires to close the selected apparatus unit AU2 and therefore momentarily operates the master close key MCK. The closing of contacts *a* of key MCK completes an energizing circuit for the upper winding of relay MC through conductor 211, contacts *e* of relay RC, contacts *c* of relay T2, contacts *b* of relay C1, conductor 302 and contacts *b* of relay CR. The closing of contacts *a* of relay MC connects relay SC in parallel with the upper winding of relay MC through conductor 301 so that relay SC closes its contacts *e* and completes a locking circuit for itself and the upper winding of relay MC through conductors 301 and 302 and contacts *b* of relay CR. The opening of contacts *b* of relay SC interrupts the heretofore described locking circuit for relay RC, and the closing of contacts *c* reestablishes the heretofore described energizing circuit for relay LS. Relays LS and LX then operate in the manner heretofore described to transmit the closing code of four impulses in the same manner that the four impulses of the selection code were transmitted, except that in the case of the closing code a pause occurs between the first and second impulses and between the second and third impulses.

At the dispatcher's office, the four impulses of the closing code effect the operation of relays LX, C1 to C4, inclusive, CT, OD and PR in the same manner as the four impulses of the selection code. The energization of relay C1 in response to the first impulse of the closing code, however, completes an energizing circuit for the pause relay PS through conductor 308, contacts *b* of relay LO, conductor 204, contacts *c* of relay PR, conductor 307, contacts *f* of relay C3, contacts *h* of relay C2, contacts *i* of relay C1, contacts *m* of relay CH, conductor 314, contacts *c* and *e* of relay MC, conductor 310, contacts *a* of relay OD, contacts *b* of relay C4, contacts *g* of relay C1, conductor 302 and contacts *b* of relay CR. The opening of contacts *b* of relay PS prevents LS from being reenergized when relay LX closes its contacts *d* at the termination of the first impulse. Consequently, at the termination of the first impulse of the closing code, relay PR drops out after a time delay and closes its contacts *b* to complete an energizing circuit for code register relay P'12 through conductor 212, contacts *c* of relay C1, contacts *d* of relay C2, contacts *d* of relay C3, contacts *b* of relay PR, conductor 310, contacts *a* of relay OD, contacts *b* of relay C4, contacts *g* of relay C1, conductor 302 and contacts *b* of relay CR. The closing of contacts *a* of relay P'12 completes a locking circuit for this relay through conductor 302 and contacts *b* of relay CR. The opening of contacts *c* of relay PR interrupts the heretofore described circuit for relay PS so that it drops out and by closing its contacts *b* re-

21

establishes the energizing circuit of relay LS to effect the transmission of the second impulse of the closing code.

When relay C2 is energized in response to the second impulse, its contacts *g* complete an energizing circuit for the pause relay PS through conductor 308, contacts *b* of relay LO, conductor 284, contacts *c* of relay PR, conductor 307, contacts *f* of relay C3, contacts *g* of relay C2, conductor 315, contacts *a* of relay CH, conductor 316, contacts *a* of relay OD, contacts *b* of relay C4, contacts *g* of relay C1, conductor 302 and contacts *b* of relay CR. The opening of contacts *b* of relay PS again prevents relay LS from being re-energized when relay LX closes its contacts *d* at the termination of the second impulse. Consequently, time relay PR drops out after the second impulse has been terminated for a predetermined time and by closing its contacts *b* completes an energizing circuit for code register relay P23 through conductor 213, contacts *e* of relay C2, contacts *d* of relay C3, contacts *b* of relay PR, conductor 310, contacts *a* of relay OD, contacts *b* of relay C4, contacts *g* of relay C1, conductor 302 and contacts *b* of relay CR. The closing of contacts *a* of relay P23 completes a locking circuit for this relay through conductor 302 and contacts *b* of relay CR.

The opening of contacts *c* of relay PR interrupts the heretofore described circuit for pause relay PS so that by closing its contacts *b* it re-establishes the energizing circuit of relay LS to effect the transmission of the third impulse of the closing code.

The opening of contacts *f* of relay C4, when it is energized in response to the fourth impulse of the closing code, interrupts the energizing circuit of relay LS so that this relay remains de-energized after the termination of the fourth impulse. Consequently, time relay PR drops out and by closing its contacts *d* completes an energizing circuit for relay CR through conductor 320, contacts *b* of relay RC, contacts *a* of relay T2, contacts *f* of relay C4, contacts *a* of relay SC, contacts *d* of relay PR, contacts *e* of relay T1, contacts *f* of relay CH, conductor 311 and contacts *f* of relay RL. The opening of contacts *b* of relay CR interrupts the locking circuits for relays C1 to C4, inclusive, P12, P23, MC and SC. The opening of contacts *f* of relay C4 interrupts the heretofore described energizing circuit for relay CR, and the closing of contacts *f* of relay C1 re-establishes the heretofore described energizing circuit for relay OD.

Therefore, at the end of the closing code, relays S2, CH, T1, T2, OD and BR at the dispatcher's office are energized.

At the substation, the four impulses of the closing code effect the operation of relays L'X', C'1 to C'4, inclusive, C'T', R'C', O'D' and P'R' in the same manner as the four impulses of the selection code. The pause between the first and second impulses is of sufficient duration to allow relay P'R' to drop out and close its contacts *b*, thereby completing an energizing circuit for code register relay P'12 through conductor 512, contacts *g* of relay C'1, contacts *d* of relay C'2, contacts *f* of relay C'3, contacts *b* of relay P'R', contacts *b* of relay L'O', contacts *a* of relay O'D', contacts *b* of relay C'4, contacts *c* of relay C'1, conductor 400 and contacts *b* of relay C'R'. By closing its contacts *a*, relay P'12 completes a locking circuit for itself through conductor 400 and contacts *b* of relay C'R'.

The pause between the second and third im-

22

pulses of the sending code again causes relay P'R' to drop out, and the closing of its contacts *b* completes an energizing circuit for code register relay P'23 through conductor 513, contacts *e* of relay C'2, contacts *f* of relay C'3, contacts *b* of relay P'R', contacts *b* of relay L'O', contacts *a* of relay O'D', contacts *b* of relay C'4, contacts *c* of relay C'1, conductor 400 and contacts *b* of relay C'R'. By closing its contacts *a*, relay P'23 completes a locking circuit for itself through conductor 400 and contacts *b* of relay C'R'.

At the termination of the fourth and last impulse of the closing code, relay P'R' is again de-energized. By opening its contacts *a*, it effects the deenergization of relay O'D', which after being deenergized for a predetermined time closes its contacts *f* and completes an energizing circuit for the master close relay M'C' through contacts *h* of relay P34, contacts *e* of relay P'12, contacts *e* of relay P'23, conductor 515, contacts *a* of relay T'2, contacts *f* of relay C'4, contacts *b* of relay O'D', contacts *d* of relay P'R', conductor 404, contacts *e* of relay T'1, conductor 412, contacts *k* of relay C'H', conductor 403, contacts *f* of relay L'O', conductor 503 and contact *h* of relay R'L'. The closing of contacts *c* of relay M'C' completes an energizing circuit for the closing winding CC of apparatus unit AU2 through contacts *e* of relay R'C', conductor 516, contacts *g* of relay C'4, conductor 417, contacts *e* of relay M'C', conductor 517 and contacts *k* of relay S'2.

The closing of apparatus unit AU2 opens its auxiliary contacts *b* and closes its contacts *a* so that the upper winding of relay I'A'2 is short circuited and the lower winding of relay I'A'2 is energized to reverse the flux in the relay and cause it to drop out quickly. The closing of contacts *a* of apparatus unit AU2 also completes a shunt circuit around relay I'T' and an energizing circuit for relay I'C' through contacts *e* of relay S'2, conductor 503, relay I'C', conductor 511, contacts *e* of relay T'2, conductor 413 and contacts *a* of relay S'2. The closing of contacts *e* of relay I'C' completes an energizing circuit for relay C'R' through conductor 505, contacts *g* of relay R'C', contacts *e* of relay I'C', contacts *a* of relay M'C', contacts *d* of relay I'T' and contacts *c* of relay R'C'. The opening of contacts *b* of relay C'R' interrupts the locking circuits of relays C'1 to C'4, inclusive, P'12 and P'23 so that these relays drop out. The closing of contacts *d* of relay C'1 re-establishes the energizing circuit of relay O'D'. The opening of contacts *e* of relay P'12 and of contacts *e* of relay P'23 interrupts the heretofore described energizing circuit for relay M'C', which in turn by opening its contacts *a* interrupts the energizing circuit of relay C'R'.

Therefore, at the end of the closing code, relays R'C', S'2, C'H', T'1, T'2, O'D', I'C', I'A'1, and I'A'3 to I'A'5, inclusive, at the substation are energized, and the apparatus at the substation is now ready to transmit a close indication code to the dispatcher's office. This close indication code is the same as the closing code; namely, four positive impulses with a pause between the first and second impulses and between the second and third impulses.

The closing of contacts *b* of relay C'R' at the termination of the closing code completes an energizing circuit for relay S'C' through contacts *b* of relay C'R', conductor 400, contacts *b* of relay C'1, contacts *c* of relay T'2, conductor 518, contacts *b* of relay I'T', contacts *c* of relay I'C', con-

tacts *a* of relay R'C', conductor 408, and contacts *h* of relay L'O'. The closing of contacts *c* of relay S'C' completes a locking circuit for this relay through contacts *h* of relay L'O', conductor 408, contacts *c* of relay S'C', conductor 400 and contacts *b* of relay C'R'. The opening of contacts *b* of relay S'C' interrupts the locking circuit of relay R'C', and the closing of contacts *e* of relay S'C' reestablishes the energizing circuit for relay L'S' through contacts *b* of relay P'S', contacts *b* of relay L'X', conductor 408, contacts *e* of relay S'C', contacts *f* of relay C'4, conductor 410 and contacts *d* of relay C'R'.

The apparatus at the substation then operates to effect the transmission of the four impulses of the close indication code in the same manner that the four impulses of the selection check code were transmitted, except when C'1 is energized by the first impulse the energizing circuit for relay P'S' is completed through contacts *c* of relay P'R', contacts *h* of relay C'3, contacts *h* of relay C'2, contacts *i* of relay C'1, contacts *e* of relay C'H', conductor 414, contact *a* of relay I'C', conductor 408, contacts *e* of relay S'C', contacts *f* of relay C'4, conductor 410 and contacts *d* of relay C'R'. Consequently, at the end of the first impulse, relay P'R' is deenergized and by closing its contacts *b* completes the heretofore described circuit for relay P'12.

When C'2 is energized by the second impulse, the energizing circuit for relay P'S' is completed through contacts *c* of relay P'R', contacts *h* of relay C'3, contacts *g* of relay C'2, contacts *c* of relay C'H', conductor 408, contacts *e* of relay S'C', contacts *f* of relay C'4, conductor 410 and contacts *d* of relay C'R'. Consequently, at the end of the second impulse, relay P'R' is deenergized and by closing its contacts *b* completes the heretofore described circuit for relay P'23.

At the completion of the fourth impulse, relay P'R' is again deenergized and closes its contacts *d* to complete an energizing circuit for relay M'C' through contacts *h* of relay P'24, contacts *e* of relay P'12, contacts *e* of relay P'23, conductor 515, contacts *a* of relay T'2, contacts *i* of relay C'4, contacts *a* of relay S'C', contacts *d* of relay P'R', conductor 404, contacts *e* of relay T'1, conductor 412, contacts *k* of relay C'H', conductor 408, contacts *f* of relay L'O', conductor 503 and contacts *h* of relay R'L'. The closing of contacts *a* of relay M'C' completes an energizing circuit for the upper winding of relay I'A'2 through contacts *c* of relay S'2, conductor 418, contacts *f* of relay R'C', contacts *e* of relay I'C', contacts *a* of relay M'C', contacts *d* of relay I'T', contacts *d* of relay R'C', conductor 413, contacts *a* of relay S'2 and contacts *a* of apparatus unit AU2. The closing of contacts *a* of relay I'A'2 completes a locking circuit for the upper winding of this relay through contacts *a* of apparatus unit AU2.

The closing of contacts *c* of relay M'C' completes an energizing circuit for relay C'R' through contacts *h* of relay R'C' and conductor 505. The opening of contacts *b* of relay C'R' interrupts the holding circuits of relays C'1 to C'4, inclusive, P'12, P'23 and S'C'. The closing of contacts *d* of relay C'1 reestablishes the energizing circuit for relay O'D', and the opening of contacts *e* of relay P'12 and of contacts *e* of relay P'23 interrupts the energizing circuit of relay M'C', which in turn by opening its contacts *c* interrupts the energizing circuit of relay C'R'.

Therefore, at the termination of the close indication code, relays S'2, C'H', T'1, T'2, O'D',

I'C', and I'A'1 to I'A'3, inclusive, are energized at the substation.

The four impulses of the close indication code effect the same operation of relays LR, LX, C1 to C4, inclusive, CT, PR, OD, P12 and P23 at the dispatcher's office as the closing code did, except that the energization of relay CT at the end of the first impulse of the indication code completes an energizing circuit for relay RC through contacts *e* of relay CT, contacts *b* of relay SC, conductor 311 and contacts *f* of relay RL.

At the termination of the fourth impulse of the indication code, time relays PR and OD successively become deenergized and drop out and a circuit is completed for the lower winding of relay MC through contacts *h* of relay P'24, contacts *e* of relay P'12, contacts *e* of relay P'23, conductor 215, contacts *c* of relay RC, contacts *a* of relay T'2, contacts *i* of relay C'4, contacts *b* of relay OD, contacts *d* of relay PR, contacts *e* of relay T'1, contacts *i* of relay CH, conductor 311 and contacts *f* of relay RL. The energization of relay MC completes an energizing circuit for relay IR2 through resistor RR2, contacts *g* of relay S'2, conductor 108, contacts *g* of relay MC, conductor 215, contacts *g* of relay C'4 and contacts *a* of relay RC. By closing its contacts *c*, relay IR2 completes a locking circuit for itself through resistor RR2. The closing of contacts *e* of relay IR2 completes a circuit for red lamp R2 through contacts *b* of key DK2, and the opening of contacts *b* of relay IR2 opens the circuits of the white lamp W2 and the green lamp G2. The lighting of the red lamp R2 informs the dispatcher that the apparatus unit AU2 at the remote station is in its closed position.

The closing of contacts *i* of relay IR2 completes an energizing circuit for relay CR through contacts *i* of relay S'2, contacts *i* of relay IR2, conductor 108, contacts *i* of relay MC, conductor 215, contacts *g* of relay RC, conductor 316, contacts *g* of relay P'23, contacts *e* of relay ST, contacts *b* of key MTK, contacts *b* of key CHK, contacts *b* of key MCK and conductor 320. The opening of contacts *b* of relay CR interrupts the locking circuits of relays C1 to C4, inclusive, P12 and P23. The closing of contacts *f* of relay C1 reestablishes the energizing circuit for relay OD, and the opening of contacts *g* of relay P'23 interrupts the energizing circuit of relay CR. The opening of contacts *e* of relay P'23 interrupts the heretofore described circuit for relay MC.

Therefore, at the termination of the close indication code, relays ST, S'2, CH, T'2, T'1, RC, OD, BR and IR2 at the dispatcher's office are energized.

The dispatcher may now restore the equipment at the dispatcher's office and at the substation by restoring the select key SK2 to its normal position. The closing of the contacts *b* of key SK2 completes an energizing circuit for the lower winding of relay LO through contacts *g* of relay ST, conductor 108, contacts *b* of key SK4, contacts *b* of key SK3, contacts *b* of key SK2, contacts *b* of key SK1, conductor 300, contacts *d* of relay C1 and contacts *b* of relay LX. The closing of contacts *c* of relay LO completes a locking circuit for the upper winding of relay LO through contacts *h* of relay RL. The closing of contacts *a* of relay LO completes an energizing circuit for relay LS through contacts *b* of relay PS, contacts *d* of relay LX, conductor 303, contacts *b* of relay RL, conductor 304, contacts *e* of relay OD, conductor 321, contacts *b* of key ERK, conductor 311, contacts *a*

of relay LO, conductor 300, contacts *d* of relay C1 and contacts *b* of relay LX. The energization of relay LS causes an impulse to be transmitted over line conductors L1 and L2 so that relays LR and LX are energized. The closing of contacts *a* of relay LX establishes the heretofore described energizing circuits for relays C1 and PR, and by closing its contacts *a*, relay C1 completes a locking circuit for itself and relay PR in the manner heretofore described. The opening of contacts *d* of relay LX interrupts the energizing circuit of relay LS so that it drops out and terminates the reset impulse being sent over line conductors L1 and L2. The closing of contacts *b* of relay LX completes the energization of relay CT in the manner heretofore described through contacts *e* of relay C1. The opening of contacts *d* of relay C1 prevents relay LS from being reenergized when relay LX closes its contact *d*. Consequently, relay PR drops out after a time delay and closes its contacts *b* to complete the heretofore described energizing circuit for relay P12. The closing of contacts *a* of relay P12 completes a locking circuit for this relay through conductor 302 and contacts *b* of relay CR. The opening of contacts *a* of relay PR interrupts the energizing circuit for time relay OD, which after a time delay closes its contacts *d* and completes an energizing circuit for relay CR through conductor 320, contacts *d* of relay OD, conductor 220, contacts *e* of relay LO, conductor 226 and contacts *d* of key EMK. Relay OD also completes an energizing circuit for relay RL through the upper winding of release relay RL, conductor 317, contacts *f* of relay OD, contacts *b* of relay C4, contacts *g* of relay C1, conductor 302 and contacts *b* of relay CR. Due to the fact that relay CR has a slightly slower operating characteristic, relay RL operates before relay CR opens its contacts *b*. The closing of contacts *a* of relay RL completes a locking circuit for this relay through the lower winding of relay RL, contacts *a* of relay RL, conductor 218 and contacts *k* of relay C1 so that relay RL remains energized after relay CR picks up. The opening of contacts *f* of relay RL interrupts the heretofore described locking circuits for relays S2, CH, T1, T2 and RC. The opening of contacts *h* of relay RL interrupts the holding circuits of relays LO and ST. The opening of contacts *c* of relay CH interrupts the heretofore described circuit for amber lamp A2.

The closing of contacts *e* of relay RL completes a shunt circuit around contacts *e* of relay LO, conductor 228 and contacts *d* of key EMK in the energizing circuit for relay CR through conductor 320, contacts *d* of relay OD and conductor 320. The closing of contacts *a* of relay CR completes a holding circuit for the lower winding of relay RL through contacts *a* of relay RL, conductor 218 and contacts *c* of relay RL. The opening of contacts *b* of relay CR interrupts the circuit of upper winding of relay RL and the holding circuits of relays C1, P12 and CT. The closing of contacts *f* of relay C1 reestablishes the heretofore described energizing circuit for relay OD, which by opening its contacts *d* interrupts the energizing circuit for relay CR. By opening its contacts *a*, relay CR interrupts the holding circuit for the lower winding of relay RL so that it drops out.

The closing of contacts *d* of relay C1 reestablishes the original circuit for start lamp STL which informs the dispatcher that the apparatus at the dispatcher's office is in its normal-at-rest position, ready for further operation.

At the substation, the single reset impulse ef-

fects the operation of relays L'R', L'X', C'1, C'T', P'R' and P'12 in the same manner as the first impulse of the closing code. The closing of contacts *e* of relay C'T' completes an energizing circuit for relay R'C' through conductor 402, contacts *b* of relay S'C', conductor 401 and conductor 500.

At the termination of the reset impulse, time delay relays P'R' and O'D' drop out in succession, and relay O'D' completes an energizing circuit for the upper winding of relay R'L' through contacts *b* of relay O'D', contacts *b* of relay C'4, contacts *c* of relay C1, conductor 400 and contacts *b* of relay C'R'. The closing of contacts *a* of relay R'L' completes a holding circuit for the relay through its lower winding, conductor 402 and contacts *e* of relay C'1. The opening of contacts *h* of relay R'L' interrupts the holding circuit of relays T'1, T'2, S'2 and C'H'. The opening of contacts *e* of relay S'2 interrupts the energizing circuit of relay I'C'. The closing of contacts *e* of relay R'L' completes an energizing circuit for relay C'R' through contacts *d* of relay O'D' and conductor 505. The opening of contacts *b* of relay C'R' interrupts the energizing circuits of relays C'1, P'12 and C'T' and of the upper winding of relay R'L'. The closing of contacts *d* of relay C'1 reestablishes the energizing circuit for relay O'D'. The opening of contacts *d* of relay O'D' interrupts the energizing circuit of relay C'R', and the opening of contacts *a* of relay C'R' interrupts the energizing circuit of relays R'C' and R'L' so that the substation equipment is back to its normal-at-rest position with relays O'D' and I'A' to I'A'5, inclusive, energized.

If the dispatcher should want to open the apparatus unit AU2 after closing it and before resetting the supervisory equipment, he may do so by momentarily operating the master tripping key MTK after the red lamp R2 is lighted. The operation of the master tripping key MTK completes an energizing circuit for the upper winding of relay MT through contacts *a* of key MTK, conductor 211, contacts *e* of relay RC, contacts *c* of relay T2, contacts *b* of relay C1, conductor 302 and contacts *b* of relay CR. The closing of contacts *a* of relay MT connects relay SC in parallel with the upper winding of relay MT through conductor 301 so that relay SC closes its contacts *e* and completes a locking circuit for itself and the upper winding of relay MT through conductors 301 and 302 and contacts *b* of relay CR. The opening of contacts *b* of relay SC interrupts the locking circuit of relay RC, and the closing of contacts *c* of relay SC completes the heretofore described energizing circuit for relay LS to effect the transmission of the tripping code of four impulses over line conductors L1 and L2. This tripping code includes two pauses, one between the second and third impulses and the other between the third and fourth impulses, which pauses are effected in the manner heretofore described by the energization of relay PS.

At the dispatcher's office, the four impulses of the tripping code effect the operation of relays LX, C1 to C4, inclusive, CT, OD and PR in the same manner as the four impulses of the closing code. When relay C2 is energized in response to the second impulse, its contacts *g* complete an energizing circuit for relay PS through conductor 308, contacts *b* of relay LO, conductor 204, contacts *c* of relay PR, conductor 307, contacts *f* of relay C3, contacts *g* of relay C2, conductor 315, contacts *a* of relay CH, conductor 310, contacts *a* of relay OD, contacts *b* of relay C4, contacts *g* of relay C1, conductor 302 and contacts *b* of relay

CR. When relay C3 is energized by the third impulse of the tripping code, its contacts *i* complete an energizing circuit for relay PS through conductor 306, contacts *b* of relay LO, conductor 204, contacts *c* of relay PR, conductor 307, contacts *i* of relay C3, conductor 308, contacts *e* of relay CH, conductor 208, contacts *f* of relay P12, conductor 318, contacts *a* of relay OD, contacts *b* of relay C4, contacts *g* of relay C1, conductor 302 and contacts *b* of relay CR.

When relay PR drops out and closes its contacts *d* in response to the pause between the second and third impulses, relay P23 is energized and completes a locking circuit for itself in the manner heretofore described. Similarly, when relay PR drops out in response to the pause between the third and fourth impulses of the tripping code, relay P34 is energized and completes a locking circuit for itself.

At the termination of the tripping code, time relay PR drops out and completes the heretofore described energizing circuit for relay CR, which by opening its contacts *b* interrupts the locking circuits of relay C1 to C4, inclusive, P23, P34 and SC and the circuit of the upper winding of relay MT. The opening of contacts *i* of relay C4 interrupts the energizing circuit for relay CR, and the closing of contacts *f* of relay C1 reestablishes the heretofore described energizing circuit for relay OD.

At the substation, the four impulses of the tripping code effect the operation of relays L'R', L'X', C'1 to C'4, inclusive, C'T', O'D' and P'R' in the same manner as the four impulses of the closing code. The pause between the second and third impulses is of sufficient duration to allow relay P'R' to drop out and close its contacts *b* thereby completing the heretofore described circuit for code register relay P'23. Similarly, the pause between the third and fourth impulses of the tripping code is of sufficient duration to allow relay P'R' to drop out and complete the heretofore described energizing circuit for code register relay P'34.

At the termination of the fourth and last impulse of the tripping code, relay P'R' is again deenergized and by opening its contacts *a* effects after a time delay the deenergization of relay O'D'. The closing of contacts *f* of relay O'D' completes an energizing circuit for master tripping relay M'T' through contacts *i* of relay P'34, contacts *d* of relay P'12, contacts *e* of relay P'23, conductor 515, contacts *a* of relay T'2, contacts *i* of relay C'4, contacts *f* of relay O'D', contacts *d* of relay P'R', conductor 404, contacts *e* of relay T'1, conductor 412, contacts *k* of relay C'H', conductor 403, contacts *f* of relay L'O', conductor 503 and contacts *h* of relay R'L'. The closing of contacts *c* of relay M'T' completes an energizing circuit for the trip coil TC of apparatus unit AU2 through contacts *e* of relay R'C', conductor 516, contacts *g* of relay C'4, conductor 417, contacts *b* of relay M'C', contacts *e* of relay M'T', conductor 522 and contacts *i* of relay S'2.

The opening of apparatus unit AU2 opens its contacts *a* and closes its contacts *b* so that the upper winding of relay I'A'2 is short circuited and the lower winding of relay I'A'2 is energized to reverse the flux in the relay and cause it to drop out quickly. The closing of contacts *b* of apparatus unit AU2 also completes a shunt circuit around relay I'C' and an energizing circuit for relay I'T' through contacts *b* of apparatus unit AU2, contacts *a* of relay S'2, conductor 413, contacts *e* of relay T'2 and conductor 511. The

closing of contacts *e* of relay I'T' completes an energizing circuit for relay C'R' through conductor 505, contacts *g* of relay R'C', contacts *d* of relay I'C', contacts *a* of relay M'T', contacts *e* of relay I'T' and contacts *c* of relay R'C'. The opening of contacts *b* of relay C'R' restores the apparatus at the substation to the same condition it was in at the end of the closing code, except that relay I'T' instead of relay I'C' is energized. The apparatus at the substation is now ready to transmit a trip indication code to the dispatcher's office.

The closing of contacts *b* of relay C'R' at the termination of the tripping code completes an energizing circuit for relay S'C' through contacts *b* of relay C'R', conductor 400, contacts *b* of relay C'1, contacts *c* of relay T'2, conductor 518, contacts *c* of relay I'T', contacts *b* of relay I'C', contacts *a* of relay R'C', conductor 408 and contacts *h* of relay L'O'. The opening of contacts *b* of relay S'C' deenergizes relay R'C'. The closing of contacts *c* of relay S'C' reestablishes the energizing circuit for relay L'S' in the manner heretofore described so that the four impulses of the trip indication code are transmitted over line conductors L1 and L2. This trip indication code, which is the same as the tripping code, includes two pauses, one between the second and third impulses and the other between the third and fourth impulses, which are effected in the manner heretofore described by the energization of relay P'S'.

At the substation, the four impulses of the trip indication code effect the operation of relays L'X', C'1 to C'4, inclusive, C'T', O'D' and P'R' in the same manner as the four impulses of the tripping code. When relay C'2 is energized in response to the second impulse, its contacts *g* complete an energizing circuit for relay P'S' through contacts *c* of relay P'R', contacts *h* of relay C'3, contacts *g* of relay C'2, contacts *c* of relay C'H', conductor 406 and contacts *e* of relay S'C', contacts *f* of relay C'4, conductor 410 and contacts *d* of relay C'R'. When relay C'3 is energized in response to the third impulse, an energizing circuit is completed for relay P'S' through contacts *c* of relay P'R', contacts *i* of relay C'3, contacts *a* of relay C'H', conductor 422, contacts *f* of relay P'12, conductor 406, contacts *e* of relay S'C', contacts *f* of relay C'4, conductor 410 and contacts *d* of relay C'R'. When relay P'R' drops out in response to the pause between the second and third impulses, relay P'23 is energized and completes a locking circuit for itself in the manner heretofore described. Similarly, when relay P'R' drops out in response to the pause between the third and fourth impulses, relay P'34 is energized and completes a locking circuit for itself.

At the termination of the trip indication code, time relay P'R' drops out and completes an energizing circuit for relay M'T' through contact *i* of relay P'34, contacts *d* of relay P'12, contacts *e* of relay P'23, conductor 515, contacts *a* of relay T'2, contacts *i* of relay C'4, contacts *d* of relay S'C', contacts *d* of relay P'R', conductor 404, contacts *e* of relay T'1, conductor 412, contacts *k* of relay C'H', conductor 403, contacts *f* of relay L'O', conductor 503, and contacts *h* of relay R'L'. The closing of contacts *a* of relay M'T' energizes lower winding of relay I'A'2 through contacts *c* of relay S'2, conductor 418, contacts *f* of relay R'C', contacts *d* of relay I'C', contacts *a* of relay M'T', contacts *e* of relay I'T', contacts *d* of relay R'C', conductor 413, contacts

a of relay $S'2$ and contacts *a* of relay $A'U'2$. The closing of contacts *c* of relay $M'T'$ completes an energizing circuit for relay $C'R'$ through contacts *h* of relay $R'C'$ and conductor 505. The energizing of relay $C'R'$ effects the restoration of the apparatus at the substation in the manner heretofore described to the same condition it was in at the time the transmission of the trip indication code was initiated except relay $R'C'$ is now deenergized.

At the dispatcher's office, the four impulses of the trip indication code effect the operation of relays LR , LX , $C1$ to $C4$, inclusive, CT , OD and PR in the same manner as the four impulses of the close indication code. The pause between the second and third impulses is of sufficient duration to allow relay PR to drop out and close its contacts thereby completing the heretofore described circuit for code register relay $P23$. Similarly, the pause between the third and fourth impulses of the trip indication code is of sufficient duration to allow relay PR to drop out and complete the heretofore described energizing circuit for relay $P34$.

At the termination of the fourth and last impulse of the trip indication code, relay PR is again deenergized and by opening its contacts *a* effects the deenergization of relay OD so that an energizing circuit for the lower winding of relay MT is completed through contacts *g* of relay $P34$, contacts *d* of relay $P12$, contacts *e* of relay $P23$, conductor 215, contacts *c* of relay RC , contacts *a* of relay $T2$, contacts *f* of relay $C4$, contacts *b* of relay OD , contacts *d* of relay PR , contacts *e* of relay $T1$, contacts *f* of relay CH , conductor 311 and contacts *f* of relay RL . The energization of relay MT completes a shunt circuit around the winding of relay $IR2$ through contacts *a* of relay $IR2$, contacts *e* of relay $S2$, conductor 113, contacts *e* of relay MT , contacts *b* of relay MC , conductor 216, contacts *g* of relay $C4$ and contacts *a* of relay RC . By opening its contacts *e*, relay $IR2$ extinguishes red lamp $R2$ and by closing its contacts *b* completes a series lighting circuit for lamps $G2$ and $W2$ through contacts *c* of disagreement key $DK2$. By moving disagreement key $DK2$ to its other position, white lamp $W2$ is extinguished. By closing its contacts *f*, relay $IR2$ completes an energizing circuit for relay CR through conductor 320, contacts *b* of master close key MCK , contacts *b* of master check key CHK , contacts *b* of master trip key MTK , contacts *e* of relay ST , contacts *g* of relay $P23$, conductor 318, contacts *g* of relay RC , conductor 217, contacts *g* of relay MT , conductor 105 contacts *f* of relay $IR2$ and contacts *f* of relay $S2$. The opening of contacts *b* of relay CR restores the apparatus at the dispatcher's office to the position in which it was at the beginning of the trip indication code except relay RC is now energized.

If after effecting the operation of the supervisory equipment so as to select apparatus unit $AU2$ in the manner heretofore described the dispatcher wishes to check his indication of the position of the selected apparatus unit $AU2$ without performing any control operation thereof, he may do so by momentarily moving master check key CHK to its other position. Since contacts *a* of key CHK are connected in parallel with contacts *a* of key MCK and contacts *c* of key CHK are connected in parallel with contacts *a* of key MTK , the operation of key CHK effects the energizations of the windings of relays MC and MT in

the manner heretofore described so that relay SC is energized and reestablishes the energization of relay LS to transmit the indication check code which comprises four impulses with a pause between successive impulses, each pause being effected in the manner heretofore described by relay PS . A circuit is completed for relay PS through conductor 306, contacts *b* of relay LO , conductor 204, contacts *c* of relay PR , conductor 307, contacts *c* of relay MT , contacts *c* of relay MC , conductor 310, contacts *a* of relay OD , contacts *b* of relay $C4$, contacts *g* of relay $C1$, conductor 302 and contacts *b* of relay CR .

The four impulses of the indication check code effect the same operation of relays LR , LX , $C1$ to $C4$, inclusive, CT , PR , OD and PS as the impulses of the other codes did, except that relay $P12$ is energized during the pause between the first and second impulses, relay $P23$ is energized during the pause between the second and third impulses and relay $P34$ is energized during the pause between the third and fourth impulses. At the termination of the fourth and last impulse of the indication check code, relay PR becomes deenergized and drops out and completes an energizing circuit for relay CR through conductor 320, contacts *b* of relay RC , contacts *a* of relay $T2$, contacts *f* of relay $C4$, contacts *a* of relay SC , contacts *d* of relay PR , contacts *e* of relay $T1$, contacts *f* of relay CH , conductor 311 and contacts *f* of relay RL . Relay CR , by opening its contacts *b*, restores the apparatus at the dispatcher's office to the condition it was in when the indication check code was initiated except relay RC is now deenergized.

At the substation, the four impulses of the indication check code effect the same operation of relays $L'R'$, $L'X'$, $C'1$ to $C'4$, inclusive, $C'T'$, $R'C'$, $P'R'$ and $O'D'$ in the same manner as other codes originating at the dispatcher's office. The pause between the first and second impulses effects the energization of relay $P'12$, the pause between the second and third impulses effects the energization of relay $P'23$ and the pause between the third and fourth impulses effects the energization of relay $P'34$ in the manner heretofore described. At the termination of the fourth and last impulse of the indication check code, the relays $P'R'$ and $O'D'$ successively become deenergized and drop out and complete an energizing circuit for relay $C'R'$ through conductor 505, contacts *g* of relay $P'34$, contacts *e* of relay $P'12$, contacts *e* of relay $P'23$, conductor 515, contacts *a* of relay $T'2$, contacts *f* of relay $C'4$, contacts *f* of relay $O'D'$, contacts *d* of relay $P'R'$, conductor 404, contacts *e* of relay $T'1$, conductor 412, contacts *k* of relay $C'H'$, conductor 403, contacts *f* of relay $L'O'$, conductor 503 and contacts *h* of relay $R'L'$. Relay $C'R'$, by opening its contacts *b*, restores the apparatus at the substation to the position it occupied at the beginning of the indication check code except relay $R'C'$ is now energized.

The closing of contacts *b* of relay $C'R'$ after the transmission of the indication check code reestablishes the heretofore described energizing circuit for relay $S'C'$ so that the apparatus at the substation transmits an indication code corresponding to the positions of relay $I'T'$ and $I'C'$. If relay $I'C'$ is energized, a close indication code is transmitted, whereas if relay $I'T'$ is energized, a trip indication code is transmitted in the manner heretofore described.

It will now be assumed that the supervisory equipment at the dispatcher's office and the sub-

station is in the normal-at-rest position and apparatus unit AU2 is opened by its associated protective devices (not shown) so that contacts *a* of apparatus unit AU2 are opened and contacts *b* are closed. The opening of contacts *a* interrupts the energizing circuit of the upper winding of relay I'A'2, and the closing of contacts *b* completes an energizing circuit for the lower winding of relay I'A'2 so that the flux in the relay is reversed and the relay immediately drops out, thereby completing an energizing circuit for relay S'T' through conductor 423, contacts *d* of relay I'A'2, conductor 508, contacts *b* of relay R'C', contacts *f* of relay T'1, conductor 521, contacts *f* of relay C'1 and contacts *d* of relay L'X'. By closing its contacts *a*, relay S'T' completes a locking circuit for itself through conductor 428 and contacts *b* of relay R'L'. By closing its contacts *e*, relay S'T' completes an energizing circuit for relay S'C' through contacts *h* of relay L'O', conductor 408, contacts *e* of relay S'T', conductor 424, contacts *d* of relay T'1, conductor 508, contacts *d* of relay T'2, contacts *b* of relay C'1, conductor 408 and contacts *b* of relay C'R'. By closing its contacts *e*, relay S'C' completes the heretofore described energizing circuit for relay L'S' to cause the selection code of four impulses with a pause between the third and fourth impulses, which is the code for apparatus unit AU2 to be transmitted over line conductors L1 and L2 in the manner heretofore described.

When relay C'3 is energized in response to the third impulse of the code, relay P'S' is energized to effect a pause between the third and fourth impulses in the manner heretofore described. This energizing circuit for relay P'S' is through contacts *c* of relay P'R', contacts *i* of relay C'3, contacts *b* of relay C'H', conductor 411, contacts *i* of relay S'T', conductor 425, contacts *b* of relay I'A'2, conductor 510, contacts *f* of relay P'23, contacts *f* of relay P'12, conductor 408, contacts *e* of relay S'C', contacts *f* of relay C'4, conductor 410 and contacts *d* of relay C'R'.

At the completion of the fourth and last impulse of the selection code, relay P'R' is deenergized and drops out after a time delay, thereby completing an energizing circuit for relay S'2 through conductor 608, contacts *e* of relay P'34, contacts *d* of relay P'23, contacts *b* of relay P'12, conductor 502, contacts *b* of relay T'2, contacts *i* of relay C'4, contacts *a* of relay S'C', contacts *d* of relay P'R', conductor 404, contacts *h* of relay T'1, conductor 503 and contacts *h* of relay R'L. By closing its contacts *g*, relay S'2 completes a locking circuit for itself through conductor 403, contacts *f* of relay L'O', conductor 503 and contacts *h* of relay R'L'. The closing of contacts *e* of relay S'2 completes through conductor 603 a series energizing circuit for relays I'T' and I'C'. Relay I'T' completes an energizing circuit for relay C'R' through conductor 505, contacts *b* of relay T'1, contacts *a* of relay I'T', conductor 428 and contacts *b* of relay R'L'. By opening its contacts *b*, relay P'R' deenergizes relays C'1 to C'4, inclusive, P'34 and S'C' which were energized and locked up during the transmission of the selection code. The closing of contacts *d* of relay C'1 reestablishes the energizing circuit of relay O'D'. By closing its contacts *a*, relay C'R' completes an energizing circuit for relay T'1 through conductor 407, contacts *f* of relay C'H', contacts *d* of relay L'O', contacts *d* of relay R'L', conductor 506 and contacts *a* of relay C'R'. By closing its contacts *c*, relay T'1 completes a locking circuit for itself through conductor 403, con-

tacts *f* of relay L'O', conductor 503 and contacts *h* of relay R'L'. By opening its contacts *b*, relay T'1 interrupts the energizing circuit for relay C'R' so that at the end of the selection code relays S'2, T'1, ST, I'A'1, I'A'3, I'A'4, I'A'5, I'C', I'T' and O'D' at the substation are energized.

At the dispatcher's office, the four impulses of the selection code effect the operation of relays LR, LX, C1 to C4, inclusive, PR, OD and P34 in the manner heretofore described.

The energization of relay LX in response to the first impulse of the selection code interrupts the heretofore described circuit for start lamp STL. When relay LX is deenergized at the termination of the first impulse and relay CT is energized in the manner heretofore described, relay RC is energized through contacts *e* of relay CT, contacts *b* of relay SC, conductor 311 and contacts *f* of relay RL. The closing of contacts *a* of relay RC completes a shunt circuit around the winding of relay BR through contacts *b* of relay T1, conductor 518, contacts *d* of relay LO and conductor 221. By closing its contacts *b*, relay BR completes an energizing circuit for alarm bell AB and by closing its contacts *d* completes a circuit for alarm lamp AL.

At the completion of the fourth and last impulse of the selection code, relays PR and OD drop out in succession and relay OD completes an energizing circuit for relay S2 through conductor 104, contacts *e* of relay P34, contacts *d* of relay P23, contacts *b* of relay P12, conductor 208, contacts *b* of relay T2, contacts *i* of relay C4, contacts *b* of relay OD, contacts *d* of relay PR, contacts *f* of relay T1, conductor 311 and contacts *f* of relay RL. By closing its contacts *c*, relay S2 completes a locking circuit for itself through conductor 311 and contacts *f* of relay RL. The closing of contacts *i* of relay S2 completes an energizing circuit for relay CR through contacts *i* of relay IR2, conductor 109, contacts *d* of relay MC, conductor 209, contacts *d* of relay T1 and conductor 320. By opening its contacts *b*, relay CR interrupts the energizing circuits of relays C1 to C4, inclusive, and P34 so that relay OD is reenergized through contacts *f* of relay C1. Relay CR also completes an energizing circuit for relay T1 through contacts *b* of relay CH, conductor 210, contacts *f* of relay RL and contacts *a* of relay CR. By closing its contacts *g*, relay T1 completes a locking circuit for itself and by opening its contacts *d* interrupts the energizing circuit of relay CR so that at the end of the selection code relays S2, T1, RC, OD, and IR2 remain energized at the dispatcher's office.

The dispatcher's office is now ready to transmit a selection check code to the substation, and this operation is effected by the relay T1 completing an energizing circuit for relay SC through conductor 301, contacts *b* of relay ST, conductor 222, contacts *c* of relay T1, contacts *f* of relay T2, contacts *b* of relay C1, conductor 302 and contacts *b* of relay CR. By closing its contacts *e*, relay SC completes the heretofore described locking circuit for itself, and by closing its contacts *c*, relay SC completes the heretofore described energizing circuit for relay LS which effects the transmission of the selection check code of four impulses with a pause between the third and fourth impulses. This selection code effects the operation of relays C1 to C4, inclusive, P34, PR, OD and CT at the dispatcher's office in the manner heretofore described. The pause between the third and fourth impulses is effected by relay

PS in the manner heretofore described, this relay being energized in response to the third impulse through a circuit including conductor 306, contacts *b* of relay LO, conductor 204, contacts *c* of relay PR, conductor 307, contacts *f* of relay C3, conductor 308, contacts *b* of relay CH, conductor 309, contacts *k* of relay S2, conductor 310, contacts *a* of relay OD, contacts *b* of relay C4, contacts *g* of relay C1, conductor 302 and contacts *b* of relay CR.

When relay PR drops out at the termination of the fourth and last impulse of the selection check code, a circuit is completed for relay CH through contacts *e* of relay T1, contacts *d* of relay PR, contacts *a* of relay SC, contacts *f* of relay C4, contacts *b* of relay T2, conductor 208, contacts *b* of relay P12, contacts *d* of relay P23, contacts *e* of relay P34, conductor 104, contacts *c* of relay S2, conductor 311 and contacts *f* of relay RL. Relay CH completes the heretofore described locking circuit for itself and also a circuit for lighting amber lamp A2 through contacts *c* of relay CH, conductor 312, contacts *a* of relay S2 and amber lamp A2. Relay CH also completes an energizing circuit for relay CR through conductor 320, contacts *a* of relay T1, contacts *d* of relay T2 and contacts *g* of relay CH. By opening its contacts *b*, relay CR deenergizes relays C1 to C4, inclusive, P34 and SC so that relay OD is reenergized through contacts *f* of relay C1. Relay CR also completes an energizing circuit for relay T2 through contacts *k* of relay CH, conductor 210, contacts *f* of relay RL and contacts *a* of relay CR. By closing its contacts *e*, relay T2 completes a locking circuit for itself and by opening its contacts *d* interrupts the energizing circuit for relay CR so that at the end of the selection check code relays S2, T2, T1, CH, OD and IR2 are energized at the dispatcher's office.

At the substation, the four impulses of the selection check code effect the operation of relays L'R', L'X', C'1 to C'4, inclusive, C'T', C'R', O'D', R'C' and P'34 in the manner heretofore described.

When relays F'R' and O'D' drop out in response to the termination of the fourth and last impulse of the selection check code, a circuit is completed for relay C'H' if the correct selection check code is received at the substation. This circuit for relay C'H' is through conductor 412, contacts *e* of relay T'1, conductor 404, contacts *d* of relay P'R', contacts *f* of relay O'D', contacts *i* of relay C'4, contacts *b* of relay T'2, conductor 502, contacts *b* of relay P'12, contacts *d* of relay P'23, contacts *e* of relay P'34, conductor 600, contacts *g* of relay S'2, conductor 403, contacts *f* of relay L'O', conductor 503 and contacts *h* of relay R'L'. By closing its contacts *k*, relay C'H' completes a locking circuit for itself through conductor 403, contacts *f* of relay L'O', conductor 503 and contacts *h* of relay R'L' and by closing its contacts *g* completes an energizing circuit for relay C'R' through contacts *f* of relay T'2 and conductor 505. By opening its contacts *b*, relay C'R' interrupts the locking circuits for relays C'1 to C'4, inclusive, and P'34 and by closing its contacts *a* completes an energizing circuit for relay T'2 through conductor 506, contacts *d* of relay R'L', contacts *d* of relay L'O' and contacts *i* of relay C'H'. By closing its contacts *g*, relay T'2 completes the locking circuit for itself, and by closing its contacts *e*, relay T'2 completes a shunt circuit around relay I'C' through conductor 511, contacts *e* of relay T'2, conductor 413, contacts *a* of relay S'2 and

contacts *b* of apparatus unit AU2. By opening its contacts *b*, relay T'2 interrupts the energizing circuit of relay C'R' so that at the termination of the selection check code relays S'2, C'H', T'1, T'2, R'C', I'T', I'A'1, I'A'3 to I'A'5 at the substation are energized.

The equipment at the substation now transmits a trip indication code to the dispatcher's office and energizes relay I'A'2 in the manner heretofore described, this operation being initiated by relay C'R' completing the energizing circuit for relay S'C' through contacts *h* of relay L'O', conductor 408, contacts *a* of relay R'C', contacts *b* of relay I'C', contacts *c* of relay I'T', conductor 518, contacts *c* of relay T'2, contacts *b* of relay C'1, conductor 400 and contacts *b* of relay C'R'.

At the dispatcher's office, the trip indication code, which consists of four impulses with a pause between the second and third impulses and between the third and fourth impulses, effects in the manner heretofore described the lighting of lamps G2 and W2 and causes lamp R2 to be extinguished. The dropping out of relay IR2 in response to the trip indication code also completes an energizing circuit for the upper winding of relay LO through contacts *d* of relay ST, contacts *g* of relay P23, conductor 316, contacts *g* of relay RC, conductor 217, contacts *g* of relay MT, conductor 105, contacts *f* of relay IR2 and contacts *i* of relay S2. Relay LO completes a locking circuit for its upper winding through contacts *c* of relay LO and contacts *h* of relay RL so that relay LO is also energized after the termination of the trip indication code. Consequently, when relay CR becomes deenergized and closes its contacts *b* at the termination of the trip indication code, an energizing circuit is completed for relay LS through contacts *b* of relay PS, contacts *d* of relay LX, conductor 303, contacts *b* of relay RL, conductor 304, contacts *e* of relay OD, conductor 321, contacts *b* of key ERK, conductor 111, contacts *a* of relay LO, conductor 300, contacts *d* of relay C1 and contacts *b* of relay LX. Relay LX causes a single reset impulse to be transmitted over conductors L1 and L2, and this single reset impulse effects in the manner heretofore described the resetting of the supervisory apparatus at both stations to the normal-at-rest condition, except that the star lamp STL at the dispatcher's office is not lighted because its circuit is open at contacts *c* of relay BR.

The ringing of alarm bell AB and the lighting of alarm lamp AL informs the dispatcher that an apparatus unit at the substation has changed its position, and the lighting of green lamp G2 and of white lamp W2 informs him that it was the apparatus unit AU2 which changed its position. By momentarily operating key ERK and thereby closing its contacts *a*, the dispatcher completes an energizing circuit for relay BR, which by closing its contacts *a* completes a locking circuit for itself. The opening of contacts *b* of relay BR stops the ringing of alarm bell AB, the opening of contacts *d* of relay BR extinguishes the alarm lamp AL and the closing of contacts *c* of relay BR reestablishes the heretofore described circuit for lighting start lamp STL.

The closing of contacts *e* of key ERK completes through conductor 117 an energizing circuit for the upper winding of relay LO, and this

relay by closing its contacts *c* completes a locking circuit for its upper winding through contacts *h* of relay RL. Therefore, when the dispatcher restores key ERK to its normal position, the closing of contacts *b* of this key ERK completes the heretofore described circuit for relay LS to cause a single reset impulse to be transmitted over line conductors L₁ and L₂, thereby causing the apparatus at the dispatcher's office and substation to go through another reset operation.

If during the transmission of an indication code from the substation the apparatus unit, whose position is being transmitted, changes its position, the associated indication relay is not restored to its energized condition at the termination of the indication code. For example, if while a close indication code of apparatus unit AU₂ is being transmitted, this apparatus unit opens so that its auxiliary contacts *b* complete a shunt circuit around relay I'C' and complete an energizing circuit for relay I'T', the energization of relay M'C' in the manner heretofore described at the termination of the fourth impulse of the close indication code does not complete the heretofore described circuit for the upper winding of relay I'A'2 because this circuit is now open at contacts *e* of relay I'C' and contacts *d* of relay I'T'. Therefore, as soon as the dispatcher has restored the supervisory equipment to its normal-at-rest position by restoring select key SK2 to its normal position, deenergized relay I'A'2 is operative in the manner heretofore described to initiate the operation of the supervisory equipment so that the lamps W₂ and G₂ are operated at the dispatcher's office to inform the operator that the apparatus unit AU₂ has operated and is in its open position.

If for any reason all four impulses of a code are not properly transmitted over the line conductors L₁ and L₂, the release relay at the receiving station is energized to effect the resetting of the associated supervisory equipment. For example, if all of the four impulses of a code being transmitted from the dispatcher's office to the substation are not received by the substation supervisory equipment, relay C'4 is not energized when relay O'D' drops out at the end of the code. Consequently the closing of contacts *b* of relay O'D' completes the heretofore described energizing circuit for the upper winding of relay R'L' through contacts *b* of relay O'D', contacts *b* of relay C'4, contacts *c* of relay C'1, conductor 400 and contacts *b* of relay C'R. The energization of relay R'L' then effects the resetting of the substation supervisory equipment in the manner heretofore described.

If all of the four impulses of a code being transmitted from the substation to the dispatcher's office are not received by the dispatcher's office supervisory equipment, the dropping out of relay OD at the end of the code completes an energizing circuit for the upper winding of relay RL through conductor 317, contacts *f* of relay OD, contacts *b* of relay C4, contacts *g* of relay C1, conductor 302 and contacts *b* of relay CR. The energization of relay RL then effects the resetting of the supervisory equipment at the dispatcher's office in the manner heretofore described.

If for any reason a code of more than four impulses is received at either station, the associated release relay is energized to reset the associated supervisory equipment. For example, if a fifth impulse is received at the dispatcher's office while relay C4 is energized, a circuit is

completed for the upper winding of release relay RL through conductor 317, contacts *c* of relay C4, contact *c* of relay C2, contact *b* of relay CT, and contacts *a* of relay LX. Similary, at the substation a fifth impulse effects the completion of an energizing circuit for the upper winding of release relay R'L' through contacts *c* of relay C'4, contacts *c* of relay C'2, contacts *b* of relay C'T' and contacts *a* of relay L'X'.

10 Therefore, until relay CR at the dispatcher's office and relay C'R' at the substation are deenergized after a code of impulses has been transmitted, reset relays RL and R'L' are operative to reset the selective apparatus in case any number of impulses other than the required predetermined number are transmitted during the transmission of a code.

While I have shown my invention in connection with a supervisory system in which the apparatus units are all in one substation, it is

20 obvious to those skilled in the art that the five apparatus units may be located in different substations, each of which is equipped with a supervisory equipment similar to that shown in Figs. 4 to 6, inclusive, and connected to line conductors L₁ and L₂. For example, assume that apparatus units AU₁ and AU₂ are in one substation X and apparatus units AU₃ to AU₅, inclusive, are in another substation Y. The supervisory equipment at substation X would be the

25 same as that shown in Figs. 4 to 6 inclusive, except that relays S'3, S'4, S'5, I'A'3, I'A'4 and I'A'5 would be omitted and in substation Y the supervisory equipment would be the same as that shown in Figs. 4 to 6, inclusive, except that relays S'1, S'2, I'A'1 and I'A'2 would be omitted. In each substation, the energizing circuit of each omitted selection relay is connected

30 to the winding of relay L'O', as indicated by the dotted line in Fig. 5 for selection relays S'1 and S'2, so that when a selection code is transmitted over line conductors L₁ and L₂ it is received in each substation, but in one substation a selection is made and in the other substation the lockout relay L'O' is energized. The closing of contacts *a* of relay L'O' completes a locking circuit for the relay through contacts *f* of relay R'L'.

35 The opening of contacts *d*, *f* and *g* of relay L'O' in the locked out substation prevents the associated supervisory equipment from doing anything except receive code and energize its counting relays C'1 to C'4, inclusive, which at the end of each code are released by the energization of relay C'R', the circuit of which is completed through conductor 505, contacts *d* of relay O'D', contacts *c* of relay L'O' and contacts *e* of relay C'4.

40 When the single reset impulse is transmitted over the line conductors, it effects the energization of the upper winding R'L' at the locked out substation, in the same manner as at the other substation, to reset the associated supervisory equipment.

45 When two or more substation equipments are connected to a single pair of line conductors, the first substation equipment that starts to transmit a selection code renders the other substation equipments inoperative to transmit a code by interrupting the circuits of start relays S'T' thereof. For example, the energization of relay

50 L'X' and relay C'1 at a substation which has not started to transmit a selection code interrupts the circuit of relay S'T' at contacts *d* of relay L'X' and contacts *f* of relay C'1 and later by contacts *b* of relay R'C'.

55 If, however, two or more substation supervisory

equipments start to transmit codes simultaneously, they will send out impulses in unison until one stops for a code pause while the other is transmitting an impulse. This impulse locks out the substation equipment which has stopped to make a pause while the other substation equipment continues to transmit the rest of its code. This result is accomplished as a result of relay P'G' which is energized each time relay P'S' at the substation is energized to effect a code pause. When relay L'X' closes its contacts *b* at the termination of an impulse preceding a code pause, a circuit is completed for relay P'G' through contacts *c* of relay P'S', contacts *b* of relay L'X', conductor 406, contacts *e* of relay S'C', contacts *f* of relay C'4, conductor 418 and contacts *d* of relay C'R'. The closing of contacts *c* of relay P'G' completes a shunt circuit around contacts *b* of relay L'X' in the energizing circuit of P'G'. If while relay P'G' is energized an impulse is transmitted over line conductors L₁ and L₂, the closing of contacts *a* of relay L'X' at the substation whose relay P'G' is energized completes an energizing circuit for the associated lockout relay L'O' through contacts *a* of relay P'G' and contacts *a* of relay P'S'. Relay L'O' completes a locking circuit for itself through its contacts *a* and contacts *f* of relay R'L' and locks out the associated substation supervisory equipment until a reset impulse is transmitted over line conductors L₁ and L₂ to energize the upper winding of release relay R'L'.

In a similar manner, the supervisory equipment at the dispatcher's office is locked out in case an impulse for any reason is received by line relay LR while pause relay PS is energized. Each time pause relay PS is energized, a circuit is completed for relay PG through contacts *c* of relay PS, contacts *d* of relay LX, conductor 303, contacts *b* of relay RL, conductor 304, contacts *c* of relay SC, conductor 305, contacts *d* of relay CR, conductor 203 and contacts *f* of relay C4. The closing of contacts *c* of relay PG completes a shunt circuit around contacts *d* of relay LX in the energizing circuit of relay PG. If while relay PG is energized relay LX closes its contacts *a* in response to an impulse being transmitted over line conductors L₁ and L₂, an energizing circuit is completed for the upper winding of relay LO through conductor 117, contacts *a* of relay PG, contacts *a* of relay PS and contacts *a* of relay LX. The closing of contacts *c* of relay LO completes a locking circuit for the upper winding of relay LO through contacts *h* of release relay RL.

The closing of contacts *a* of relay LO completes an energizing circuit for relay LS so that at the end of the code a fifth impulse is transmitted which effects the energization of relays RL and R'L' to effect the resetting of the selecting apparatus in the manner heretofore described. The energizing circuit of relay LS, which effects the transmission of the fifth or resetting impulse, is through contacts *b* of relay PS, contacts *d* of relay LX, conductor 303, contacts *b* of relay RL, conductor 304, contacts *e* of relay OD, conductor 321, contacts *b* of relay ERK, conductor 111, contacts *a* of relay LO, conductor 300 and contacts *e* of relay C4.

While I have shown the impulse communication channel between the dispatcher's office and the substation as being a two-wire metallic channel, it is evident that it could be one wire and the ground or any other channel permitting the transmission of direct current impulses. If it is desired to operate the equipment over a car-

rier current channel, the contacts of relays LS and L'S' at the dispatcher's office and substation respectively are connected in any well-known manner to cause the carrier transmitters to send impulses and line relays LR and L'R' are connected to be operated by the carrier receiver.

When an exposed open wire channel is used and insulating transformers are required for protective reasons, the equipment can be operated by applying alternating current impulses to the channel. In such a case, line relays LR and L'R' are arranged in any suitable manner so that they respond to alternating current impulses, and relays LS and L'S' connect sources of alternating current instead of direct current to line conductors L₁ and L₂ through the insulating transformers.

My system is unique in that it looks at the space between the impulses rather than at the length of the impulses. Also, my system responds to a predetermined number of impulses. These features present solutions to many problems involved in application of supervisory control equipment to various types of channels, such as joint use of the carrier channel for protective relaying, impulse telemetering, communication and supervisory control.

While I have illustrated a supervisory control system for controlling only five apparatus units, it will be evident that the number of controlled apparatus units may be readily increased merely by increasing the number of impulses in each selection and selection check code while maintaining the same four impulse control codes as heretofore described. For example, by using selection and selection check codes of five impulses, the system can be used to supervise as many as sixteen apparatus units. By using selection and selection check codes of six impulses, thirty-two apparatus units can be supervised, and by increasing the number of impulses to seven, sixty-four apparatus units can be supervised. To enable the system to be used to supervise these additional apparatus units, it would be necessary to add at each point an additional counting relay and an additional pause relay for each additional impulse in the selection and selection check codes and an additional selection relay and indication relay for each additional apparatus unit.

While I have, in accordance with the Patent Statutes, shown and described my invention as applied to a particular system and as embodying various devices diagrammatically indicated, changes and modifications will be obvious to those skilled in the art, and I therefore aim in the appended claims to cover all such changes and modifications as fall within the true spirit and scope of my invention.

What I claim as new and desire to secure by Letters Patent of the United States is:

1. In a supervisory control system in which any one of a plurality of units at one point is arranged to be selected and supervised from another point over a single circuit interconnecting the two points, the combination at one of said points of a sender relay adapted when energized to cause a current impulse to flow through the circuit, a receiver relay responsive to a current impulse flowing through the circuit for effecting the immediate deenergization of said sender relay to terminate the current impulse, a chain of counting relays controlled by said receiver relay so that they are successively energized in response to the transmission of a series of impulses through the circuit, a pause relay controlling said

sender relay so that it is inoperative while said pause relay is energized, means for selectively effecting the energization of said pause relay in response to the energization of any desired relay of said chain of counting relays, and means controlled by said pause relay for effecting the de-energization thereof after it has been energized for a predetermined time which is longer than the time interval normally produced between successive impulses by the operation of said receiver relay.

2. In a supervisory control system in which any one of a plurality of units at one point is arranged to be selected and supervised from another point over a single circuit interconnecting the two points, the combination at one of said points of a sender relay adapted when energized to cause a current impulse to flow through the circuit, a receiver relay responsive to a current impulse flowing through the circuit for effecting the immediate deenergization of said sender relay to terminate the current impulse, a chain of counting relays controlled by said receiver relay so that they are successively energized in response to the transmission of a series of impulses through said circuit, means responsive to the energization of a predetermined relay of said chain of counting relays for rendering said sender relay inoperative, a pause relay controlling said sender relay so that it is inoperative while said pause relay is energized, means for selectively effecting the energization of said pause relay in response to the energization of any desired relay of said chain of counting relays which is arranged to be energized prior to said predetermined relay of said chain, and means responsive to the absence of a current impulse in said circuit for a predetermined time interval for effecting the deenergization of said pause relay.

3. In a supervisory control system in which any one of a plurality of units at one point is arranged to be selected and supervised from another point over a single circuit interconnecting the two points, the combination at one of said points of a sender relay adapted when energized to cause a current impulse to flow through the circuit, a receiver relay responsive to a current impulse flowing through the circuit for effecting the immediate deenergization of said sender relay to terminate the current impulse, a chain of counting relays controlled by said receiver relay so that they are successively energized and locked up in response to the transmission of a series of impulses through said circuit, means responsive to the energization of a predetermined relay of said chain of counting relays for rendering said sender relay inoperative, a pause relay controlling said sender relay so that it is inoperative while said pause relay is energized, means for selectively effecting the energization of said pause relay in response to the energization of any desired relay of said chain of counting relays which is arranged to be energized prior to said predetermined relay, means responsive to the absence of a current impulse in said circuit for a predetermined time interval for effecting the deenergization of said pause relay, and means responsive to the absence of a current impulse in said circuit for a predetermined longer time interval than said first mentioned predetermined time interval for effecting the deenergization of the locked up counting relays.

4. In a supervisory control system in which any one of a plurality of units at one point is arranged to be selected and supervised from another

point over a single circuit interconnecting the two points, the combination at one of said points of means for transmitting over said circuit from said one point a plurality of codes of current impulses, all of said codes having the same number of impulses and different from each other by the length of time elapsing between the successive impulses thereof, a chain of counting relays responsive to said impulses, said chain having the same number of relays as the number of impulses in each code whereby each counting relay is energized and locked up individually by the corresponding impulse of each code, an individual register relay for each time interval between the successive impulses of said codes, means responsive to the time interval between any two impulses of a code exceeding a predetermined value for effecting the energization and locking up of the register relay individual to that time interval, a plurality of control devices, and means responsive to the absence of a current impulse in said circuit for a predetermined time interval after the last relay of said chain is energized by a code of impulses for selectively effecting the operation of said devices in accordance with the energized condition of said register relays.

5. In a supervisory control system in which any one of a plurality of units at one point is arranged to be selected and supervised from another point over a single circuit interconnecting the two points, the combination at one of said points of means for transmitting over said circuit from said one point a plurality of codes of current impulses, all of said codes having the same number of impulses and differing from each other by the length of time elapsing between the successive impulses thereof, a chain of counting relays responsive to said impulses, said chain having the same number of relays as the number of impulses in each code whereby each counting relay is energized and locked up individually by the corresponding impulse of each code, an individual register relay for each time interval between the successive impulses of said codes, means responsive to the time interval between any two impulses of a code exceeding a predetermined value for effecting the energization and locking up of the register relay individual to that time interval, a group of relays, and means responsive to the absence of a current impulse in said circuit for a predetermined time interval after the last impulse of a code is terminated for selectively energizing and locking up a relay of said group of relays depending upon the energized conditions of said register relays and for subsequently effecting the deenergization of said counting relays and the locked up register relays.

6. In a supervisory control system in which any one of a plurality of units at one point is arranged to be selected and supervised from another point over a single circuit interconnecting the two points, the combination at one of said points of means for transmitting over said circuit from said one point a plurality of codes of current impulses, all of said codes having the same number of impulses and differing from each other by the length of time elapsing between the successive impulses thereof, a chain of counting relays responsive to said impulses, said chain having the same number of relays as the number of impulses in each code whereby each counting relay is energized and locked up individually by the corresponding impulse of each code, an individual register relay for each time interval between the successive impulses of said codes, means re-

41

sponsive to the time interval between any two impulses of a code exceeding a predetermined value for effecting the energization and locking up of the register relay individual to that time interval, a group of relays, means responsive to the absence of a current impulse in said circuit for a predetermined time interval after the last impulse of a code is terminated for selectively energizing and locking up a relay of said group of relays depending upon the energized conditions of said register relays, and means responsive to the energization of said relay of said group of relays for effecting the deenergization of said locked up counting and register relays.

7. In a supervisory control system in which any one of a plurality of units at one point is arranged to be selected from another point over a single circuit interconnecting the two points, the combination of means at each point for transmitting over the circuit a code of current impulses individual to each unit, all of said codes having the same number of impulses of the same character and duration and differing from each other by the length of the time elapsing between the successive impulses, a selection relay at each point individual to each unit, means at each point selectively controlled by the duration of the pauses in said codes for effecting at the termination of a code the operation of the associated selection relay individual to the unit whose code was transmitted, means at each point responsive to the operation of a selection relay thereof in response to a code transmitted from the other point for effecting the transmission over the circuit of the code individual to the unit corresponding to the selected selection relay, a check relay at each point, and means at each point selectively controlled by the duration of the pauses in said last mentioned code for effecting at the termination thereof the operation of the check relays at the respective points when the transmitted code effecting the operation of a selection relay is the same as the code transmitted in response to the operation of that selection relay.

8. In a supervisory control system in which any one of a plurality of units at one point is arranged to be selected from another point over a single circuit interconnecting the two points, the combination of means at each point for transmitting over the circuit a plurality of codes of impulses, all of said codes having the same number of impulses of the same character and duration and differing from each other by the length of the time interval elapsing between the successive impulses, a chain of counting relays at each point responsive to said impulses, an individual register relay at each point for each time interval between said impulses, means responsive to the time interval between any two impulses exceeding a predetermined value for effecting the energization and locking up of the register relay individual to that time interval, means at each point selectively operated in accordance with the energization of the associated register relays after the expiration of a predetermined time interval following the termination of a code of impulses transmitted from the respective point and after the expiration of a predetermined longer time interval following the termination of a code of impulses transmitted from the other point.

9. In a supervisory control system in which any one of a plurality of units at one point is arranged to be selected from another point over a single circuit interconnecting the two points,

42

the combination of means at each point for transmitting over the circuit a plurality of codes of impulses, all of said codes having the same number of impulses of the same character and duration and differing from each other by the length of the time interval elapsing between the successive impulses, a chain of counting relays at each point, each chain having the same number of relays as the number of impulses in each code whereby each counting relay is energized and locked up individually by the same impulse of each code, an individual register relay at each point for each time interval between the impulses of said codes, means responsive to the time interval between any two impulses of a code exceeding a predetermined value for effecting the energization and locking up of the register relay individual to that time interval, means at each point selectively operated in accordance with the energization of the associated register relays after the expiration of a predetermined time interval following the termination of a code of impulses, and means at each point controlled by said last mentioned selectively operated means at the respective point for effecting the deenergization of the associated locked up counting and register relays.

10. In a supervisory control system in which any one of a plurality of units at one point is arranged to be selected from another point over a single circuit interconnecting the two points, the combination of means at each point for transmitting over the circuit a plurality of codes of impulses, all of said codes having the same number of impulses of the same character and duration and differing from each other by the length of the time interval elapsing between the successive impulses, a chain of counting relays at each point, each chain having the same number of relays as the number of impulses in each code whereby each counting relay is energized and locked up individually by the same impulse of each code, an individual register relay at each point for each time interval between the impulses of said codes, means responsive to the time interval between any two impulses of a code exceeding a predetermined value for effecting the energization and locking up of the register relay individual to that time interval, means at each point selectively operated in accordance with the energization of the associated register relays after the expiration of a predetermined time interval following the termination of a code of impulses transmitted from the other point, and means at each point controlled by said last mentioned selected operated means at the respective point for effecting the deenergization of the associated locked up counting and register relays.

11. In a supervisory control system in which a plurality of apparatus units at one point are selectively controlled from a second point over a single circuit interconnecting said points, the combination of means at said second point for transmitting over said circuit a selection code of impulses individual to each unit, said selection codes having the same predetermined number of impulses but differing from each other by the number of long pauses between the impulses thereof, selective means at each point individual to each apparatus unit and selectively operated

in response to the transmission of a selection code, means responsive to the operation of a selective means at said one point for transmitting over said circuit a selection check code individual to the operated selective means, all of said selection check codes having the same predetermined number of impulses but differing from each other by the number of long pauses between the impulses thereof, check means at each point responsive to a transmission of said selection check code if it agrees with the operated selective means at the same point, means controlled by said check means for rendering the apparatus unit individual to the operated selective means controllable over said circuit, and means responsive to the transmission of a current impulse over said circuit during a long pause period of any of said codes while it is being transmitted for resetting the selective apparatus at each point to its normal condition.

12. In a supervisory control system in which a plurality of apparatus units at one point are selectively controlled from a second point over a single circuit interconnecting said points, the combination of means at said second point for transmitting over said circuit a selection code of impulses individual to each unit, said selection codes having the same predetermined number of impulses but differing from each other by the number of long pauses between the impulses thereof, selective means at each point individual to each apparatus unit and selectively operated in response to the transmission of a selection code, means responsive to the operation of a selective means at said one point for transmitting over said circuit a selection check code individual to the operated selective means, all of said selection check codes having the same predetermined number of impulses but differing from each other by the number of long pauses between the impulses thereof, check means at each point responsive to a transmission of said selection check code if it agrees with the operated selective means at the same point, means controlled by said check means for rendering the apparatus unit individual to the operated selective means controllable over said circuit, and means responsive to the transmission of a selection code and a selection check code of any number of current impulses other than the required predetermined number for resetting the selective apparatus at each point to its normal condition.

13. In a supervisory control system in which a plurality of apparatus units at one point are selectively controlled from a second point over a single circuit interconnecting said points, the combination of means at said second point for transmitting over said circuit a selection code of impulses individual to each unit, said selection codes having the same predetermined number of impulses but differing from each other by the number of long pauses between the impulses thereof, selective means at each point individual to each apparatus unit and selectively operated in response to the transmission of a selection code, means responsive to the operation of a selective means at said one point for transmitting over said circuit a selection check code individual to the operated selective means, all of said selection check codes having the same predetermined number of impulses but differing from each other by the number of long pauses between the impulses thereof, check means at each point responsive to a transmission of said selection check code if it agrees with the operated selective means at

the same point, means controlled by said check means for rendering the apparatus unit individual to the operated selective means controllable over said circuit and means responsive to the transmission of an impulse over said circuit within a predetermined time interval after the last impulse of any of said codes has been transmitted for resetting the selective apparatus at each point to its normal condition.

10 14. In a supervisory control system in which a plurality of apparatus units at one point are selectively controlled from a second point over a single circuit interconnecting said points and indicating means at said second point and individual 15 to each apparatus unit are selectively controlled over said circuit in accordance with the corresponding apparatus units at said one point, the combination of means at said second point for transmitting over said circuit a selection code of 20 impulses individual to each unit, said selection codes having the same predetermined number of impulses but differing from each other by the number of long pauses between the impulses thereof, selective means at each point individual 25 to each apparatus unit and selectively operated in response to the transmission of a selection code, means responsive to the operation of a selective means at said one point for transmitting over said circuit a selection check code individual to the 30 operated selective means, all of said selection check codes having the same predetermined number of impulses but differing from each other by the number of long pauses between the impulses thereof, check means at each point responsive to a transmission of said selection check code 35 if it agrees with the operated selective means at the same point, means controlled by said check means for rendering the apparatus unit individual to the operated selective means controllable 40 over said circuit, means at said second point for transmitting over said circuit a plurality of control codes of impulses after an apparatus unit has been rendered controllable over said circuit, means at said one point responsive to said control 45 codes for selectively operating the selected apparatus unit and subsequently transmitting over said circuit an indication code of impulses individual to the new position of the operated apparatus unit, said control and indication codes having the same predetermined number of impulses 50 but differing from each other by the number of long pauses between the impulses thereof, means at said second point responsive to said indication codes for selectively operating the indicating 55 means individual to the operated apparatus unit, and means responsive to the transmission of a current impulse over said circuit during a long pause period of any of said codes while it is being transmitted for resetting the selective apparatus 60 at each point to its normal condition.

15. In a supervisory control system in which a plurality of apparatus units at one point are selectively controlled from a second point over a single circuit interconnecting said points and indicating means at said second point and individual to each apparatus unit are selectively controlled over said circuit in accordance with the corresponding apparatus units at said one point, the combination of means at said second point for transmitting over said circuit a selection code of impulses individual to each unit, said selection codes having the same predetermined number of impulses but differing from each other by the number of long pauses between the 75 impulses thereof, selective means at each point

individual to each apparatus unit and selectively operated in response to the transmission of a selection code, means responsive to the operation of a selective means at said one point for transmitting over said circuit a selection check code individual to the operated selective means, all of said selection check codes having the same predetermined number of impulses but differing from each other by the number of long pauses between the impulses thereof, check means at each point responsive to a transmission of said selection check code if it agrees with the operated selective means at the same point, means controlled by said check means for rendering the apparatus unit individual to the operated selective means controllable over said circuit, means at said second point for transmitting over said circuit a plurality of control codes of impulses after an apparatus unit has been rendered controllable over said circuit, means at said one point responsive to said control codes for selectively operating the selected apparatus unit and subsequently transmitting over said circuit an indication code of impulses individual to the new position of the operated apparatus unit, said control and indication codes having the same predetermined number of impulses but differing from each other by the number of long pauses between the impulses thereof, means at said second point responsive to said indication codes for selectively operating the indicating means individual to the operated apparatus unit, and means responsive to the transmission of an impulse over said circuit within a predetermined time interval after the last impulse of any of said codes has been transmitted for resetting the selective apparatus at each point to its normal condition.

16. In a supervisory control system in which a plurality of apparatus units at one point are selectively controlled from a second point over a single circuit interconnecting said points and indicating means at said second point and individual to each apparatus unit are selectively controlled over said circuit in accordance with the corresponding apparatus units at said one point, the combination of means at said second point for transmitting over said circuit a selection code of impulses individual to each unit, said selection codes having the same predetermined number of impulses but differing from each other by the number of long pauses between the impulses thereof, selective means at each point individual to each apparatus unit and selectively operated in response to the transmission of a selection code, means responsive to the operation of a selective means at said one point for transmitting over said circuit a selection check code individual to the operated selective means, all of said selection check codes having the same predetermined number of impulses but differing from each other by the number of long pauses between the impulses thereof, check means at each point responsive to a transmission of said selection check code if it agrees with the operated selective means at the same point, means controlled by said check means for rendering the apparatus unit individual to the operated selective means controllable over said circuit, means at said second point for transmitting over said circuit a plurality of control codes of impulses after an apparatus unit has been rendered controllable over said circuit, means at said one point responsive to said control codes for selectively operating the selected apparatus unit and subsequently transmitting over said circuit an indica-

tion code of impulses individual to the new position of the operated apparatus unit, said control and indication codes having the same predetermined number of impulses but differing from each other by the number of long pauses between the impulses thereof, means at said second point responsive to said indication codes for selectively operating the indicating means individual to the operated apparatus unit, and means responsive to the transmission of more or less than said predetermined number of impulses during the transmission of said codes for resetting the selective apparatus at each point to its normal condition.

17. In a supervisory control system in which a plurality of codes of impulses are transmitted over an electric circuit interconnecting two points to selectively control supervisory apparatus at said points, the combination of means at one point for effecting the transmission over the electric circuit of a predetermined number of current impulses, a pause relay arranged when energized to produce a long pause between the transmission of successive impulses by said transmitting means, means for selectively controlling the energization of said relay so as to produce the long pause between any desired two of said current impulses, a lockout relay for rendering said first-mentioned means inoperative to effect the transmission of current impulses over the electric circuit, and means for operating said lockout relay in response to a flow of current through said circuit while said relay is energized.

18. In a supervisory control system in which a plurality of codes of impulses are transmitted over an electric circuit interconnecting two points to selectively control supervisory apparatus at said points, the combination of means at one point for effecting the transmission over the electric circuit of a predetermined number of current impulses, a chain of counting relays at said one point arranged to be energized by said impulses, a pause relay arranged when operated to produce a long pause between any two of said current impulses, means for effecting the operation of said pause relay in response to the energization of any desired counting relay, a lockout relay for rendering said first-mentioned means inoperative to effect the transmission of current impulses over the electric circuit, and means for operating said lockout relay in response to a flow of current through said circuit while said pause relay is energized.

19. In a supervisory control system in which a plurality of codes of impulses are transmitted over an electric circuit interconnecting two points to selectively control supervisory apparatus at said points, the combination of means at one point for effecting the transmission over the electric circuit of a predetermined number of current impulses, a chain of counting relays at said one point arranged to be energized by said impulses, a pause relay arranged when operated to produce a long pause between any two of said current impulses, means for effecting the operation of said pause relay in response to the energization of any desired counting relay, a plurality of selection relays at said point, means for selectively operating said selection relays in accordance with the durations of the pauses between said impulses, a lockout relay for rendering said selection relays inoperative, and means for operating said lockout relay in response to a flow of current through said circuit while said pause relay is energized.

20. In a supervisory control system in which a plurality of indicating means at one point are selectively controlled in accordance with the positions of a corresponding plurality of apparatus units at a second point over a single circuit interconnecting said points, the combination of means for selectively associating an indicating means at said one point and the corresponding apparatus unit at said second point with said single circuit whereby selected indicating means can be controlled in accordance with the position of the selected apparatus unit, a normally energized indicating relay at said second point individual to each apparatus unit, means at said second point responsive to a change in the position of an apparatus unit for effecting the deenergization of the indication relay individual thereto, means for transmitting over said circuit from said second point an indication code of impulses corresponding to the position of a selected apparatus unit whose individual indication relay is deenergized, means responsive to the transmission of an indication code of impulses for reenergizing the deenergized indication relay of the selected apparatus unit, **25**

and means responsive to a change in the position of a selected apparatus unit while its indication code of impulses is being transmitted for rendering the indication code of impulses ineffective to reenergize the indication relay of the selected apparatus unit.
